Application February 7, 1936, Serial No. 62,742

186 Claims. (Cl. 197—1)

The invention pertains to printers of the general class in which the characters are impressed upon the writing medium in succession, and concerns more especially printers of the page type 5 suitable for use in printing telegraphy, accounting machines, and for proof printing in conjunction with machines for perforating tapes to be used in the control of type casting, printing and allied typographic machines.

10 One object of the invention is to provide a high speed page printer in which the printing operation progresses from one line to the next at the same rate as between successive characters in the same line, thereby eliminating the delay usually consumed by the return movement of the paper carriage.

Another object is to provide a new and improved method of printing in which each character to be printed is simultaneously formed in all 20 of the possible character positions in a line, and wherein the position in the line at which the character thus formed is to be printed is determined by the operation of one of a series of impression elements respectively operative in the 25 various character positions.

In carrying out the foregoing objects of the invention I employ a printing head composed of a plurality of very thin flat strips arranged side by side in the form of a pack, and slidably longitudinally relative to each other. In the embodiment illustrated the strips are elongated in form, and on one edge or face of the pack formed by the strips are a plurality of spaced sets of character-forming elements in the nature of projections terminating in relatively blunt points or facets. Each set or group of elements thus constitutes a convertible type composed of delineating points or facets which may be shifted into different permutational combinations to form letters, figures and other characters as may be desired. The respective sets are spaced apart lengthwise of the printing head a distance equal to the space between adjacent characters to be printed, and upon the shifting of the strips into any predetermined combination, the same character is formed simultaneously in each of the character positions in a line. Therefore, the position in the line at which a desired character is to be printed may be determined by the operation of the proper one of a series of printing or impression elements, herein termed anvils, of which there is one for each character position. In normal operation such anvils are actuated progressively from one type to the next. By shifting 50 the strips of the pack into different character-

forming combinations during the interval between the movements of adjacent anvils, it is possible for the successive anvils to effect the printing of different characters in their proper order; and in order to change from one line to the next it is only necessary to control the proper anvils and during such control to effect a line feed by shifting the paper or other writing medium.

Letters or other characters printed by means of type formed as above set forth, while not particularly adapted for use where sharply defined characters are required, are well suited for use where exactness in character outline can be sacrificed for the sake of speed, as in recording business transactions in connection with automatic accounting and like machines; in printing telegraphic communications; and in the preparation of a record or proof simultaneously with the perforation of control forms for use in typesetting, type-writing and allied composing machines. 18 Hence while in its broader aspects the invention aims to provide a new and improved mode of printing, it has for its special object the provision of a high speed type-writing machine or printer of a practical character.

While the improved printer is adapted for control in various ways, as for instance through the use of signal responsive selecting mechanism well understood in the telegraph and allied arts, for certain purposes it is desirable that the control 30 be manual in character. Accordingly, it is another object of my invention to provide a printer having character-forming elements of the kind above referred to and arranged for selective operation by means of a keyboard.

A further object is to provide for power actuation of the machine under the control of a keyboard with selectively operable mechanisms of a relatively simple character for performing the 35 various functions.

Another object is to provide for the control of the direction of progression in printing a line character-by-character, through the provision of means for reversing at will the normal direction of progression from left to right.

Still another object is to provide a type-forming printer wherein provision is made for selecting any one of various positions in a line for the impression point, whereby to permit printing in tabular form.

Another object is to provide for the printing simultaneously of a plurality of original records on separate sheets under the control of a single character selecting mechanism.

For certain uses of the machine, as for ex- 55

ample, printing telegraphy, the characters may be printed in one font and case, as for example, upper case roman. However, as above indicated, it is contemplated that the printer may be used for the purpose of producing printed proof of matter set up simultaneously in the form of signal perforations in a control tape such as is used in the control of typographic machines, and in such machines the subject matter printed may require the use not only of upper and lower case type but also a plurality of different fonts. In such event, it is desirable that the printed proof show in addition to the character which is perforated in the control tape, the case and font of such character. Accordingly, it is an object of my invention to provide for the printing of appropriate symbols adjacent each of the characters as printed and indicating the case and font of the corresponding signal which may be perforated in an associated control tape.

The objects of the invention thus set forth, together with other and ancillary advantages are attained by the construction and arrangement illustrated in the accompanying drawings and hereinafter more particularly described, it being understood that various changes in the construction and arrangement may be made by those skilled in the art without departing from the spirit and scope of the invention as defined by the appended claims.

In the accompanying drawings:

IN GENERAL

As herein shown (Figs. 1 and 2), my improved printer comprises an elongated printing head 1 extending horizontally in the upper rear portion of the structure and of a length corresponding to the maximum length of line to be printed. On the front face of the head, spaced apart lengthwise thereof a distance determined by the letter spacing to be employed, are groups or sets of character-delineating elements arranged in two longitudinal rows one above the other and constituting convertible type 2 and 2^a (Fig. 12); and mounted for endwise front to rear movement forwardly of the head 1 is a series of impression elements or anvils 3, one for each possible character position in the line and therefore one for each of the type 2.

The delineating elements forming the type 2 and 2^a are formed on thin metallic strips (Figs. 4 and 5) capable of being shifted relative to each other to form different characters by power driven mechanism operating under the control of a series of vertical combination bars 4 selectively set in different permutational combinations as determined by a group of horizontal code bars 5 below and parallel to the printing head.

To actuate the anvils 3 to effect the printing of selected characters, I employ a power driven reciprocatory actuator 7 hereinafter termed the printing bar. This bar extends longitudinally of the machine in forwardly spaced relation to the printing head and carries a series of anvil-engaging elements in the form of pivoted dogs 6.

The power driven mechanism comprises a cam shaft 8 formed in two sections 8^a and 8^b. The former extends in a front to rear direction at the right hand end of the machine and drives

the printing head in the type-forming operation; and the latter extends longitudinally of the machine in the upper rear portion thereof and is operatively connected with the printing bar to reciprocate it in a front to rear direction. The two sections 9^a and 9^b are connected by bevel gearing 6, and the shaft is arranged for operation in successive cycles under the control of a friction clutch 10 at the extended rear end of the shaft section 9^a.

The anvils 3 are controlled for successive operation by means in the nature of a carry-over mechanism acting as an incident to the operation of one anvil in one cycle of the printing bar to condition the next anvil to be operated for engagement by its actuating dog 8 in the succeeding cycle. This mechanism includes in the preferred embodiment a series of control elements each in the form of an elongated arm 11 pivoted to each of the anvils and operatively associated with a next adjacent anvil for movement thereby in said conditioning operation. To permit a change in the direction of progression of the printing operation, the arms 11 are adapted to be shifted from association with the anvil next adjacent in one direction into a similar relation to the anvil next adjacent in the opposite direction.

While the mechanism for controlling the selective operation of the machine may vary widely in construction according to the different uses to which the machine is applied, in the present embodiment, I have provided for this purpose a keyboard 12 including a group of character keys together with a space key, arranged substantially in accordance with standard typewriter practice; a number of symbol keys controlling the printing of different symbols representing various fonts; and in addition a plurality of control or function keys. Each of the character keys and most of the function keys is operable through appropriate mechanism to initiate an operating cycle of the machine through the actuation of the cam shaft 9 under the control of the clutch 10.

Type forming

The printing head 1 comprises a main type pack 1^a for letters and other characters and an auxiliary symbol printing pack 1^b. As shown in Figs. 5 and 7, the main pack comprises a plurality of thin ribbon-like strips 13 formed with similarly shaped character-forming or delineating elements 13^a in the nature of projections equidistantly spaced apart along the forward edges of the strips and providing relatively blunt points or facets 13^b. Each strip 13 thus provides a carrier for one delineating element of each of a plurality of sets respectively constituting the convertible type 2, which are spaced apart longitudinally of the pack a distance corresponding to the spacing of the letters of a line to be printed. The strips 13 are freely shiftable longitudinally relative to each other to vary the positions of their respective elements 13^a in converting from one type character to another, and the facets 13^b composing each type face are at all times disposed in a common vertical plane in which they are relatively shifted in character formation.

The strips 13 composing the main type pack are slidable relative to each other between two guide plates 14 (see Fig. 4). As herein shown (Figs. 7 to 9) there are thirty-one of said strips 13. I have found that they may be made of

spring steel of a thickness of approximately .003 of an inch, and the spacing of the guides 14 such as to provide a space of approximately .001 of an inch between the strips to receive a film of oil or other lubricant.

The strips 13 of the type pack 1^a are shifted into different character forming combinations by means including a plurality of shifting devices 15 each comprising two drive bars 15^a and adapted for coaction with a plurality of sets of actuating surfaces formed on the individual strips. Herein two sets of opposed actuating surfaces are employed in the case of each character, and the shifting device for each character is arranged to operate upon both sets of surfaces simultaneously in the strip shifting operation.

The actuating surfaces are formed in the present instance by providing in the strips 13 slots 16 (Figs. 5 and 7) whose opposite ends are utilized to form two sets of opposed actuating surfaces or shoulders 17 and 17^a. The slots 16 are arranged in three longitudinal rows as shown, and each strip has its slots occupying generally the same but yet slightly varying endwise positions as the slots in other strips so as to form a series of holes through the pack 1^a, one for each character to be formed. Thus the pack may be said to have an A hole, a B hole, a C hole, etc., with each hole providing a set of actuating surfaces in the form of the shoulders 17 and 17^a.

One pair of drive bars 15^a is entered in each character hole and projects downwardly therefrom for connection with a combination bar 4 of the selecting mechanism. As best shown in Fig. 4, the lower ends of the bars of each pair are transversely slidable on pins 20 carried by yokes 21 rigid with the upper ends of the combination bars 4, thereby permitting a movement of separation between the bars of each pair. To permit alinement in a longitudinal row of the lower or notched portions of all the combination bars whose upper ends are connected with drive bars 15^a arranged in three rows (Fig. 10), such upper ends of the combination bars are offset laterally, as shown in Fig. 10 in the case of all but the intermediate rows.

The shifting devices are allowed to move downwardly selectively under the control of the code and combination bars 4, 5; and upon a fixed downward movement of any one pair of drive bars, the power driven actuating means, to be presently described, engages the selected pair of bars causing them to move a predetermined distance in opposite directions for the purpose of carrying into alinement all of the shoulders 17 and similarly all of the shoulders 17^a of the corresponding character hole.

When the drive bars 15^a for a given character hole are thus actuated to align vertically the corresponding sets of shoulders 17 and 17^a respectively, the strips 13 of the pack 1^a are relatively shifted so as to cause each set of type facets 13^b along the front face of the pack to be shifted in contiguous parallel planes, and thus convert the various type faces from the previously formed character to the character corresponding to the selected hole. It will be apparent, therefore, that it is necessary, for a proper shifting of the strips 13 into various character-forming combinations, that the shoulders 17 and 17^a of each character hole be properly positioned on their respective strips relative to the positions to be occupied by the elements 13^a on the strips forming the corresponding characters.

In cutting the slots 16 so as to provide the proper relation between the shoulders of each character hole, advantage is taken of the letter I as a basic character, since in forming this letter the facets 18^b of each group are arranged in vertical alignment centrally of each character position, while the shoulders 17, 17^a of the I hole are also aligned vertically. This arrangement is illustrated in Figs. 7, 8 and 9 wherein the Q, I and W holes of the pack are shown and the manner in which the strips 18 are shifted to form these several characters. In Fig. 7, the I hole and a portion of the Q hole is shown in section, and the front face of the pack is shown in elevation at the right of the figure with the facets outlining the letter I. If from this relation of the facets, it is desired to shift them into a combination representing the letter W, for example, the shifting device for the W hole is actuated as shown in Fig. 8. It will be apparent that some of the strips are shifted in one direction and some in the other. In forming the letter W, for example, such shifting provides, in the case of each type 2, four relatively inclined rows of facets with the facets in each row spaced the minimum distance apart. Similarly, the shifting of the strips from the W relation shown in Fig. 8 to the Q relation is effected by the actuation of the shifting device 16 of the Q hole (Fig. 9).

It will be observed that coincident with the positioning of the facets 18^b from the I-forming combination (Fig. 7) to the W combination (Fig. 8), a corresponding shifting of the shoulders 17, 17^a of the I-hole must occur, with the result that the ends of the slots 16 forming the I-hole respectively outline the letter W. The same relation of the facets to the arrangement of slots of the I-hole occurs in the case of the other characters, as in the case of the letter Q, Fig. 9. Thus it follows that if the slots for each character hole are so cut that their opposite end edges outline the character corresponding thereto when the ends of the slots of the I-hole are in alignment, the proper relationship is effected.

It will be observed from the foregoing that in converting the type faces from one character formation to another the strips 18 of the type pack are shifted to a greater or less degree ranging from zero to a predetermined maximum depending on the comparative contours of the two successively formed characters. Also it will be seen that some of the facets are shifted in one direction and some in the other. This is advantageous especially in the case of a printer operating at high speed in that it reduces to a minimum the kinetic energy of rapidly moving parts which must be started and stopped in each character-forming operation. Moreover, since the actuation of the strips is effected by two bars operated at high speed in opposite directions simultaneously, the time required for each character operation is reduced very substantially.

Preferably the two uppermost and the two lowermost facets 18^b of each set of character-forming elements are made substantially longer than the intermediate facets. This improves the appearance of the characters in which the facets are arranged in one or more straight rows, and in the case of the characters in which the outlines are of circular formation at their upper and lower ends the elongated facets are also advantageous.

Space or blank character formation.—To provide spaces between the words in a line, the strips 18 of the main type pack 1^a are shifted to carry

the type elements 18^a into inactive position relative to the impression elements or anvils 3. For this purpose the type-forming or delineating elements 18^a are shifted into a special formation (Fig. 6) in which they are arranged in two vertical rows disposed on opposite sides of the normal character position, with the distance between the two rows slightly greater than the width of each of the impression elements or anvils 3, so that the latter are adapted to be received between the two rows when advanced to the printing or impression point. Accordingly, the type pack 1^a is provided with an additional hole formed by slots 16 providing shoulders 17 and 17^a with which a pair of drive bars 15^a are adapted to be engaged selectively just as in the case of the other holes. To permit of the increased range of movement of the elements 18^a necessary for this purpose, it is of course essential that the groups of elements forming the type 2 be appropriately spaced along the face of the type pack so that the normal spaces between the type may accommodate the two rows of elements.

It will be observed that this method of shifting the type facets out of the path of operation of the impression elements or anvils 3, provides a very simple expedient for introducing a space between words as may be desired. In addition such space combination is available for use should it be desirable to render the anvils ineffective to print, without modifying in any way, the operation of the anvils themselves, as will appear hereinafter in connection with the description of the miscellaneous control mechanisms. In either case, the type facets may be said to be shifted to form a "blank" character.

Formation of small characters.—As in ordinary typewriter practice, certain characters, such as punctuation marks, occupy only a very small portion of the normal area required for letters, figures, etc. Thus the period, for example, requires for its formation only four facets. Accordingly, the holes in the case of such small characters are so designed as to shift, into inactive positions at opposite sides of the character position, all of the facets not necessary to be used in forming this particular character, the operation being like that described for the space blank except for the one or more facets necessary to be used.

Power drive for type forming

When a given character, including the space or blank, is to be formed along the front face of the type pack 1^a, the drive bars 15^a, which are entered in the corresponding hole of the type pack, are first moved downwardly a predetermined distance for connection with the power driven actuating means. The latter consists generally of two pairs of reciprocable actuators 23 and 24 (Figs. 4 and 3^a) which are operatively connected with the cam shaft section 9^a for movement in opposite directions.

In the present instance the actuators 23 and 24 are in the form of elongated plates extending parallel to the type pack 1 with the plates of each pair disposed on opposite sides of the pack and spaced a short distance from the plates of the other pair (Fig. 4). The drive bars 15^a entered through the character holes project from opposite sides of the pack so that when the bars of a given pair are selected for actuation, they may be engaged both above and below the pack for a movement of separation by the two pairs of oppositely moving actuators. Thus, each bar of

the selected pair is adapted to be engaged by two actuators moving in the same direction, but on opposite sides of the pack.

For the purpose of providing for an operative connection between any selected pair of drive bars 15^a and their actuators, the two pairs of plates 23 and 24 are formed with three rows of slots 27 (Fig. 3) corresponding with the three rows of character holes in the type pack; and in the opposite side edges of each of said slots is a pair of notches 28 cut to form two sets of opposed shoulders 29 and 30 (Fig. 3^a) for each character hole, the shoulders 29 being formed on the plates 23 moving in one direction, and the shoulders 30 on the plates 24 moving in opposite direction. For coaction with said shoulders 29 and 30 each drive bar is formed in each side edge with two longitudinally spaced notches 31 and 32 positioned reversely in the case of the two bars of each pair. When the bars are in raised or inactive position, the actuator plates 23 and 24 are free to slide through the notches 31 and 32, but when lowered into active position they present to the oppositely moving shoulders 29 and 30, actuating surfaces 33 and 34. Each of the surfaces 33 is formed by the upper edge portions of the notches 31, and each surface 34 is formed by an intermediate portion in the form of a lug projecting into each of the notches 32.

It will thus be seen that when any given pair of bars is lowered selectively in the corresponding character hole, each of the bars will be acted upon through the interengagement of the shoulders 29 on the plates 23 with the actuating surfaces 33, 34 of one of the drive bars 15^a, and of the shoulders 30 on the plates 24 with the actuating surfaces 33, 34 on the other drive bar of the selected pair. As a result, the drive bars will be spread apart so that the opposed shoulders 17 and 17^a at opposite ends of the corresponding character hole will be engaged by the bars and moved into vertical alinement. As an incident to such alining movement of the shoulders the strips of the type pack are shifted into proper character-forming combination, as above described.

The arrangement employed in the printing head for spacing the actuator plates 23 and 24 from each other and from the type pack is best illustrated in Fig. 4. Spacing of the inner plates 24 from the pack is accomplished by the guide plates 16, which are slotted longitudinally to receive the drive bars and held in vertically spaced relation by a narrow spacer 35 at the rear edge 55 of the type pack; and spacing of the outer plates 23 from the plates 24 is accomplished by longitudinally slotted separator plates 36. The outermost actuator plates 23 are guided at their upper and lower faces by longitudinally slotted top and bottom plates 37. The entire unit constituting the printing head 1 is supported at opposite ends by side frame members 38 (Fig. 3).

The cam means for reciprocating the two pairs of actuator plates 23 and 24 in the character-forming operation, each comprises a pair of cams 41 and 42 mounted on the section 9^a of the cam shaft 9 and respectively coacting with roller followers 44 and 45 disposed on opposite sides of the shaft. The two followers are journaled between two pairs of vertically disposed plates 46 and 47 (Fig. 2) guided for longitudinal movement in grooves 47^a cut in the top and bottom walls of a suitable housing 48, the top plate being omitted from Fig. 2 to expose the cam means. The pair of plates 46 are connected to the actu-

ator plates 23 by means of a block 49 (Figs. 2 and 4), and the plates 47 by a block 50. The plates 46 are fastened to opposite sides of the block 49 at one end thereof, and the plates 23 are reduced in width and connected to the top 5 and bottom of the block at the other end thereof. In a similar way the plates 47 are connected to the actuator plates 24 through the medium of the connector block 50.

Symbol forming

10

The sub-pack 1^b of the printing head is, as above indicated, provided for the purpose of printing identifying symbols below the characters printed by means of the main pack 1^a when the machine is used in connection with mechanism for perforating tape to be employed in the control of typographic machines employing more than one font of type. This sub-pack comprises in the present embodiment, three strips 13' separated from the main pack 1^a by a plate 51 and providing sets or groups of facets 13'' forming the convertible symbol type 2^a one for each character position along the printing head and preferably disposed below the convertible type 2. Said strips 13' are supported for endwise shifting movement in a manner generally similar to the strips 13. They are provided with a plurality of holes formed by slots 16' cut in the strips and corresponding in number to the number of symbols to be formed, there being six in the present instance, and to provide clearance for the drive bars 15^a of the main pack the strips are suitably slotted.

15

Projecting through each of the symbol holes 35 is a pair of drive bars 15^a for coaction with shoulders 17 and 17^a formed by the ends of the slots 16' just as in the case of the character holes. Because the symbols are formed simultaneously with the formation of letters, figures, 40 et cetera, formed by the convertible type 2, the same actuator plates 23 and 24 may be employed as in the case of the drive bars for the character holes of the main pack. To accommodate the additional drive bars the plates 23 and 24 are of 45 course formed with additional slots 27. In other respects, the driving connections between the drive bars and the actuating plates are the same as for the drive bars of the main pack.

45

By the proper arrangement of the shoulders 50 17 and 17^a formed by the ends of the slots 16', the three strips 13' may be shifted by the different pairs of drive bars into different relative relations so that their facets 13'' will form different symbol combinations. In the example shown in Figs. 7 to 9, one such symbol is formed by the facets relatively disposed in a stepped-relation. For other symbols, they may be arranged in oppositely stepped-relation, disposed in vertical alinement, and otherwise positioned 60 relative to each other for purposes of differentiation. In all, eight different combinations are made available by the use of three strips when shifted into different relative positions, three being necessary to provide for six symbols as herein contemplated.

55

By the arrangement set forth, the strips of the sub-pack 1^b may be shifted into different combinations to form different symbols coincidental with the operation of forming characters 70 on the main pack. For this purpose their drive bars 15^a are connected with six of the combination bars 4 for selective positioning under the control of the code bars 5, as hereinafter set forth.

75

The section 9^a of the cam shaft 9, carrying the cams 41 and 42 for actuating the printing head in the type forming operation, is suitably mounted in bearings provided by the housing 48. Its 5 rear end extends beyond the gearing connection 6 with the other section 9^b into operative relation with the clutch 10. To support the latter shaft section, the two side frame members 38 are equipped with suitable bearings 38^a. A top 10 plate 39 overlying the side frame members is extended to the left of the machine and has a bearing member 39^a secured to its underside for supporting the end of the shaft section 9^b.

Anvil operation

15 In the present embodiment the impression anvils 3 are arranged for individual reciprocation toward and from the printing head. The paper or other medium upon which the characters are printed is herein shown in the form of a sheet 20 A of the size commonly used for page printing, which sheet is positioned directly in front of the type pack; and in front of the sheet A in turn is an inked ribbon 52. The imprint on the sheet 25 A is effected by the operation of the anvils actuated by the printing bar 7 by power derived from the cam shaft 9, the latter being equipped with suitable cams for this purpose. Thus the anvils constitute impression elements operating to compress the paper A between the ribbon and the type 2 and 2^a, and this by a cam-controlled motion and with a predetermined pressure as distinguished from the usually employed sharp blow or impact.

30 The anvils 3 are in the form of plungers (Figs. 10 and 12) stamped from thin flat strips of metal and having elongated shanks 53 with impression heads 54 at their rear ends. To support the anvils for reciprocation, the machine framework 35 has two parallel bars 55 and 56 (Fig. 10) extending longitudinally of the printing head and spaced apart vertically so as to receive between them the anvils 3 and their associated control elements or arms 11. The bar 56 is formed as a part of a 40 central standard 56^a.

45 To guide the anvils for reciprocation and to maintain them in laterally spaced relation lengthwise of the printing head 1, slotted plates 57 and 58 are provided, the former secured at the rear 50 edges of the frame bars 55 and 56, and the latter secured at the forward edge of the upper frame bar 55. The anvils are constantly urged forwardly, away from the printing head by individual upright leaf springs 59 having their upper ends engaging with depending portions 60 offset forwardly from the heads 54. The lower 55 ends of the springs are suitably anchored as at 61 to the framework.

The printing bar 7 constituting the actuator for the anvils 3, is constructed so as to receive 60 and support the series of actuating dogs 8, one for each of the anvils. Said dogs are also in the form of sheet metal stampings, each being generally T-shaped in form so as to provide a forward pivotal portion 63, a shank portion 64 and a rear head portion having a depending nose 65 adapted for engagement with a notch 66 cut in the upper edge of its corresponding anvil shank 53 at the forward end of the latter.

70 The dogs 8 of the printing bar 7 (Figs. 10, 12 and 13) are supported and guided for pivotal movement in the printing bar, being arranged in laterally spaced relation corresponding to the lateral spacing of the anvil shanks 53. For this 75 purpose the bar 7 comprises two flat elongated

plates 67 and 68 supported in vertically spaced horizontal relation by spacing bars 69 and 70. The lower plate is formed with a longitudinally extending groove 71 rounded to provide a pivotal bearing surface for the forward ends of the dogs 5 8 which are provided for this purpose with correspondingly shaped projections 72. To guide the dogs for pivotal movement, the lower plate 67 is formed with slots 73 for receiving the depending nose portions 65 of the dogs; and the 10 top plate 68 is formed with slots 74 and 75 respectively receiving upper extensions 76 and 77 at the forward and rear ends respectively of the dogs. Individual leaf springs 78, mounted on the bar, bear upon the extensions 76 of the dogs 15 and constantly urge their rearward ends downwardly for purposes of engagement with the anvil shanks 53.

The printing bar 7 is suitably supported and guided at opposite ends of the machine for front 20 to rear movement (Figs. 2 and 3). For this purpose, said bar has secured to each end an elongated bar 79 guided in grooves 79^a cut in the inner side faces of two vertical side bars 80 near the upper end thereof. At their rear ends, said 25 bars are similarly guided in ways formed in the side frame members 38 and top plate 39, and between the rear end of each bar and a short plate 81 are mounted two rollers 82 and 82^a, respectively, coating with two cams 83 and 83^a on the 30 cam shaft section 9^b. In each operating cycle of the cam shaft, the printing bar executes a complete reciprocation in timed relation to the shifting of the strips 13 and 13' of the printing head 35 in the type-forming operation.

In each type-forming operation the same character or symbol is formed simultaneously in each of the character positions lengthwise of the printing head. Therefore, it will be seen that the position in the line at which the formed character and symbol are to be printed is determined by the establishment of an operative association between 40 the printing bar 7 and the particular anvil 3 which corresponds to the aforesaid position.

In normal operation the anvils 3 are actuated 45 in progressive order from left to right until the last character in a given line has been printed. Thereupon, the paper or other writing medium is advanced to a new line and a corresponding progressive actuation of the anvils commenced for 50 that line. However, it may be desirable under some circumstances, to change the normal direction of progression of the anvils in order that the printing operation may progress reversely, i. e., from right to left. Also it may sometimes be desirable that the operator be able to select 55 at will any desired position in the line for the impression point and this without regard to the previous impression point. With this in view the anvil control means comprises (Figs. 12 to 14) a 60 series of shiftable elements in the form of the elongated arms 11 and a series of pawls 85, one for each anvil.

The construction and mode of operation of the anvil arms 11, the pawls 85 coating with said 65 arms and the anvil shanks 53, may well be described first in connection with the normal progression of the printing operation from left to right. In this connection, each anvil may be said to have three positions. Thus, when any anvil 70 is in its normal position, it may be said to be in its number one position; when partially shifted so that its notch 66 is in position to receive the nose 65 of its actuating dog 8, it is in its number two position; and when moved by its dog 8 to 75

the extreme rearward position, it is in its number three position. For convenience, the first impression element 3 in the series, beginning at the left of the machine, may be referred to as the No. 1 anvil, the next No. 2, etc.

With the foregoing in view, it is one of the functions of the arms 11 and the pawls 85 to perform the aforesaid conditioning movement of one anvil, that is, movement from its number one to its number two position, as an incident to the operation of the next adjacent or preceding anvil into its number three position. It may here be noted, however, that in the case of the first anvil at the left-hand end of the series, it is necessary to provide special means to effect the aforesaid conditioning movement thereof. This means will be hereinafter described more particularly in connection with the selective control mechanisms responsive to the operation of the keyboard. For present purposes, it will suffice to say that it comprises a conditioning member 3a for the No. 1 anvil adapted for actuation by a dog 8a of the printing head in a manner similar to the anvils 3. This member, however, has no arm 11 and is moved into its number two position through the operation of a lever 86 (Fig. 19) pivotally associated therewith and actuated upon the commencement of a new line by power derived from the cam shaft 9. It will be observed that the conditioning member 3a is in the nature of a dummy anvil, having per se no printing function. For convenience, it will hereinafter be referred to as the No. 0 anvil.

Referring now to Figs. 12 and 13, each of the anvil arms 11 has its rear end pivotally connected to its corresponding anvil 3 near the rear end of the latter, which for this purpose has its depending portion 60 formed with a forwardly opening slot 67 shaped intermediate its end to receive a rounded enlargement 88 formed on the end of the arm 11. At their forward ends, the arms 11 are guided for reciprocation in a slotted plate 89 so as to be maintained in laterally spaced relation corresponding to the spacing of the anvil shanks 53. However, the arm 11 which is connected with any given anvil is normally inclined laterally relative thereto so that its forward end is associated with the next adjacent anvil. Thus, in the case of the normal progression from left to right, the arm 11 of the No. 1 anvil is inclined for association with the No. 0 anvil; the arm of the No. 2 anvil is associated with the No. 1 anvil; and the arm of the third anvil is associated with the second anvil, and so on.

In order that the advance of one anvil into its No. 3 position shall be effective to move the next adjacent anvil into its No. 2 position, each of the arms 11 of the anvils 3 carries a laterally extending lug 90 (Figs. 12 and 14) adapted for engagement by a shoulder 91 formed on the under side of the next adjacent preceding anvil shank. With this arrangement, when one anvil, for example the No. 1 anvil, is moved to its No. 3 position (Fig. 13) in the latter portion of such movement the shoulder 91 engaging with the lug 90 of the arm 11 attached to the No. 2 anvil, imparts a short movement to the latter anvil. In such movement, anvil No. 2 is conditioned for engagement by its actuating dog 8 in the next succeeding cycle of operation as above described. Similarly the subsequent actuation of the No. 2 anvil into its printing position serves to condition No. 3 anvil for the succeeding cycle.

In view of the reciprocatory character of the

printing bar 7, it is the function of each of the pawls 85 (Fig. 13) to retain its anvil in its number two position pending engagement by its actuating dog 8 in the succeeding cycle of operation. Said pawls are in the form of sheet metal stampings pivotally supported intermediate their ends on a fixed shaft 92 disposed in forwardly spaced relation to the supporting plate 89 for the arms 11. The pawls have rearwardly extending arms 83 arranged for cooperation with the forward ends of the anvil shanks 53, and for this purpose said arms 83 are formed with notches 94 adapted to receive the forward end portions 53a of the anvil shanks. The pawls are constantly urged by individual leaf springs 95 to position the upper ends of the notches 94 out of alignment with said forward end portions 53a of the anvil shanks. Thus, when the anvils are fully retracted, the forward ends of their shanks are received in the notches 94 of the pawls 85 and the latter are, therefore, in elevated position; and when an anvil is moved into its number two position, its pawl is forced downwardly by the spring 95 thereby latching the anvil in such number two position.

In normal operation the latch devices or pawls 85 are lifted individually for the purpose of permitting return movement of the anvils into their number one positions. That is to say, as an incident to the movement of one anvil into its number two position, the pawl of the preceding anvil is raised to permit return movement of that anvil in a retracting stroke of the printing bar 7. To accomplish this result, each of the pawls has its lower edge formed with a cam surface 96 (Figs. 12 and 13) which is adapted for engagement by a complementary cam surface 97 and dwell 97a formed in the upper edge of the arm 11 associated with an adjacent anvil. Accordingly, when a selected anvil is moved into its number two position by the operation of the preceding anvil into its number three position, the arm 11 of such selected anvil operates with a cam action on the pawl of the preceding anvil to lift it into position to receive the shank of said preceding anvil upon the return of the printing bar to its fully retracted position. In this connection it will be observed that during the return stroke, the pawl of the selected anvil operates through the medium of its arm 11 to hold the pawl of the preceding anvil in its elevated position.

While the forward end of a returning anvil thus enters its notch 94, the corresponding actuating dog 8 is disengaged from the anvil. For this purpose the nose 85 of each dog is provided with a cam surface 98 adapted to cooperate with a cam surface 100 on the corresponding pawl 85.

Under some circumstances, it may be desirable to effect the return to their number one positions of any of the impression anvils 3 which may have been moved to their number two positions. For this purpose each of the pawls 85, with the exception of that for the No. 0 anvil 3a, is provided with a depending tail portion 101 disposed in the path of movement of a bail in the form of a bar 102 mounted on a rock shaft 103 and operable when rocked in a counterclockwise direction (Fig. 12) to engage said tail pieces, thereby rocking the pawls to position their notches 94 in alignment with the forward ends of the shanks 53 of the anvils 3. Said shaft is adapted to be rocked by power derived from the cam shaft 8 under the control of a suitable key of the keyboard 12 (termed the blanking key) in a manner hereinafter described.

When it is desired to change the direction of

progression of the printing operation, this may be accomplished by shifting the arms 11 so as to carry their rear ends from association with the anvil shanks next adjacent in one direction into 5 association with the anvil shanks next adjacent in the opposite direction. Accordingly, the plate 89 carrying the forward ends of the arms 11 is mounted for endwise shifting movement. As shown it is supported at its opposite ends by two 10 crank pins 106 (Figs. 11 and 12) carried by parallel shafts 105 suitably supported in a frame member 107 between which and a frame member 108 the plate is guided.

The shafts 106 have fixed thereon pinions 109 15 meshing on opposite sides with two rack bars 110 and 111 suitably guided for endwise movement on the frame member 107. These rack bars and pinions are so arranged that when longitudinal movements are imparted to the bars selectively 20 the plate 89 and, therefore, the forward ends of the arms 11 are moved in one direction or the other. In Fig. 11 the parts are shown in the position occupied for normal progression from left to right, the plate 89 having been shifted to 25 the left by the movement of the lower rack bar 111 to the left, the upper bar moving at the same time to the right. To effect a reversal in the direction of progression it is only necessary to move the upper rack bar 110 to the left with a 30 corresponding movement to the right of the lower bar. In such shifting movements of the plate 89, the eccentrics in their rotation cause the guide plate to move first downward, then laterally, and finally upward. As an incident to the 35 downward movement of the plate 89, any arm 11 which has been shifted in the movement of its anvil to its No. 2 position will clear the lower rear ends of any of the pawls 85 which may be in their lower positions. The means for actuating 40 the rack bars forms a part of the key controlled mechanism to be presently described.

Cycle control by keyboard

Referring now to Figs. 2 and 17, the keyboard 45 12 comprises a group of character keys 113 including a space key 113^a for effecting the formation of a space or blank character, a case key 113^b, a plurality of symbol selecting keys 113^c (hereinafter called "font keys"), and certain 50 function keys later to be described.

The depression of any of said character and function keys serves to initiate an operating cycle by tripping the friction clutch 10. Each has a stem 114 (Fig. 15) engageable with one arm of a bell crank 115 having its other arm operative through the medium of a short abutment bar 116 to shift a codal element in the form of a notched bar or flag 117, individual leaf springs 118 acting upon the abutment bars 116 to hold the keys in their elevated positions. 55 The flags are in the form of bars notched longitudinally of their upper edges and serving to control in a well known manner the operation of transversely disposed combination bars hereinafter called "control bars." These are operative 60 selectively to govern the type-forming operation and other functions of the machine.

The flags 117 of said character and function keys are extended to the rear of the machine 70 into operative association with means for tripping the clutch 10 to initiate the machine cycles. This means is of such character so as to insure completion of one cycle and only one upon the depression of any one key. It comprises (Fig. 15) 75 a series of segments 119 one for each flag, oper-

ative upon the depression of the keys to actuate a bail 120 which in turn is operatively associated with the clutch 10. The segments 119 are mounted on a fixed laterally extending shaft 121 and each has a depending finger 119^a engaging in a notch in one of the flags so as to swing forwardly upon the rearward movement of the flag and against the action of a spring 119^b.

The bail 120 is in the form of an elongated bar supported at its opposite ends by arms 120^a upon 10 a rock shaft 122 so as to underlie the segments 119 in forwardly offset relation to the rock shaft. Extending rearwardly from the rock shaft 122 is an arm 123 entered between two spring pawls 124 and 125 suitably secured together in spaced relation and forming a latch device adapted to cooperate with a lever 126 pivoted at 126^a. The upper pawl is somewhat shorter than the lower one and normally is disposed in the path of movement of the lever 126, which latter is thereby 20 held against swinging motion under the influence of a spring 127. At its opposite or forward end the lever 126 is in the form of a bell crank having one arm operatively connected with a bar 128 hereinafter referred to as the "release bar," 25 and another arm 129 operatively connected with a transversely disposed bar 130 hereinafter called the "locking bar." The bar 130 has a plurality of notches 131 in its rear edge and to cooperate 30 with such notches, the segments 119 are formed with forwardly protruding lugs 132 normally overlying the notches 131.

With this arrangement, upon the depression of one of the keys the corresponding segment is 35 swung downwardly, its lug 132 being free to pass through the corresponding notch 131 in the locking bar. In such movement the segment engages the bail bar 120, rocking the shaft 122 and lifting the rear end of the latch operating arm 123 thereby freeing the lever 126 for movement by 40 its spring 127. In thus tripping the upper pawl 124 of the latch device, the lug 132 of the segment moves entirely through its notch 131 of the locking bar. The segment is cut away above the lug 132 to provide a notch 133 permitting movement 45 of the locking bar by the spring actuated lever 126 which imparts a corresponding movement to the release bar 128 for the purpose of tripping the clutch 10 and releasing the control bars.

As hereinbefore indicated, the clutch 10 is of 50 the friction type and may be of the construction shown in my prior Patent No. 1,962,136 issued June 12, 1934. Briefly, it comprises driving and driven elements 135 and 136, the former being connected by suitable gearing 137 with a source 55 of power, and the latter connected with the cam shaft section 9^a (see Fig. 2). The control element for this clutch is in the form of a finger 138 (Fig. 15) which when blocked against rotation holds the clutch disengaged against the action of 60 a torsion spring 138^a. In the present instance it is blocked by means of detent formed by the upper end of a bar 139 bearing at its upper end against a roller 140 and connected at its lower end with one arm 141 of a bell crank whose other 65 arm 142 is connected with the release bar 128.

Upon disengagement of the pawl 124 from the actuating lever 126, the release bar is shifted rearwardly and through its connection with the detent bar 139 withdraws the latter from engagement with the clutch finger 138 thus initiating an operating cycle. In the latter portion of such cycle, a cam 143 on the shaft 9^a operates a double roller follower 144 having rigid therewith an arm 145 connected by means of a link 146 75

with a bell crank 147 pivoted at 148. The latter has a depending arm 149 which is swung into engagement with the lever 126 to restore the clutch detent into blocking relation to the finger 138, and also to return the lever into operative association with the spring pawl 124, assuming that the operator has released the depressed key so as to cause said pawl 124 to be restored to its normal position. However, the extent of movement of the bell crank 147 by the cam 143 is such that in the event that the operator has held the operated key in its depressed position and therefore maintained the upper pawl 124 raised out of the path of the lever 126, the lower pawl 125 will have moved into blocking relation to the lever (see Fig. 15*).

It will thus be seen that if upon the depression of a given key, a corresponding segment 119 is swung far enough to actuate the bail 120 and trip the clutch 16, then in the latter portion of the ensuing cycle of the shaft 9 the blocking detent 139 is restored to a position to be engaged by the clutch finger 138 so as to terminate the cycle. In this operation the pawls 124 and 125 act in the manner of an escapement insuring termination of the cycle in the event that the operator holds the key depressed. Moreover, it will be observed that after one cycle has been initiated, the locking bar 130 serves to prevent depression of another key, for in the operation of initiating a cycle the locking bar is shifted to carry its notches 131 out of alignment with the lugs 132 of the segments 119, and the locking bar is not restored to normal position until the lever 126 is returned by the cam 143.

It will be seen that the means employed for operating the flags 117 by depressing the keys renders unnecessary a full depression of the keys. This is for the reason that the operative connection between the key and its flag is such as to permit independent movement of the flag and its segment by momentum when the key is struck a sharp blow and the tripping of the clutch is effected as an incident to the movement of the flag or control member to its operated position as distinguished from a mere depression of a key. The mechanism for accomplishing this result forms no part of the present invention but is disclosed and claimed in the copending application of Brooks Marcellus, Serial No. 201,305, filed April 11, 1938.

Key operated type selecting mechanism

The key controlled mechanism for selectively positioning the drive bars of the shifting devices 15 and 15' for the purpose of controlling the operation of the strips 13 and 13' of the printing head in forming characters and symbols, comprises a set of control bars 150, there being ten in the present instance (Figs. 16 and 17). Each is connected by a suitable motion transmitting device to one of the code bars 5 governing the selective operation of the combination bars 4 connected with the drive bars 15*.

The control bars 150 overlie the key flags 117 in transverse relation thereto (Fig. 16) and have notches 151 in their lower edges coacting with a series of notches 152 (not all of such notches being shown) in the upper edges of each of the flags in a well known manner, so that upon the depression of a given key, certain of the control bars are released for movement while others are blocked against movement.

In the present instance, the motion transmitting connection between each control bar and

its corresponding code bar is in the form of a bell crank comprising a vertical rock shaft 153 and oppositely extending arms 154 and 155 respectively connected to one of the control bars and its corresponding code bar.

Movement of the control bars 150 in various combinations as permitted by the key flags 117 appropriately notched for that purpose, is under the control of the release bar 128. The latter, it will be remembered, is operated by the spring actuated lever 126 when the latter is released by the spring pawl 124 in response to the operation of one of the keys. For this purpose, the release bar is provided with a series of slots 156 (Fig. 16), one for each of the control bars 150 and so arranged that when the release bar is shifted in response to the depression of the key, the slots will be carried into alignment with the control bars to receive the same. The control bars are constantly urged in the direction of the release bar by individual leaf springs 157, and because of the pressure thus exerted by the control bars on the release bar, the latter is supported for easy operation by two rows of vertically spaced disks or rollers 158 (Figs. 15 and 16) suitably mounted in a stationary support 159 and arranged to receive the control bars between them.

For a purpose which will hereinafter appear, the operative connection between the lower arm 30 154 and its control bar is in the form of a shoulder 155* formed at one end of an elongated notch in the upper edge of the control bar. When the control bars are released by the bar 128 for actuation by their springs 157, they move against the action of relatively weaker springs 155b, connected with the bell crank arms 154. Such movement of the control bars by their springs 157 may be limited by abutment with the stationary support 159 after passing between the disks 158.

The control bars are operated upon in each operating cycle by means of a bail 160 extending in a front to rear direction above the control bars and mounted on a shaft 161. The bail depends into elongated notches formed in the upper edges 45 of the control bars and providing shoulders 162 for engagement by the bail. The rocking shaft has a crank arm 163 at its forward end (Fig. 15) connected by a link 164 to an eccentric stud 164a on the forward end of the cam shaft section 9*. The arrangement is such that in each operating cycle incident to the depression of a given key, the bail 160 is first rocked in a direction to restore the control bars which have been permitted to move as a result of the depression of such key, and near the end of the cycle is rocked reversely to carry the bail bar 160 away from the shoulders 162 so as to free the bars for movement upon the subsequent depression of a key to start the next cycle. The operation of the bail is of course timed relative to the operation of the bell crank lever 126 by the cam 143 so as to insure restoration of the control bars when the release bar 128 is returned by said cam.

The combination bars 4 are actuated according to the setting of the code bars 5 by means controlled by the cam shaft 9. For this purpose each combination bar has an individual actuating spring 4a (Fig. 16) and its lower end is shouldered for engagement with a bail 165 carried by 70 a shaft 165a and having an actuating arm 166 operatively connected with an arm 166a of the double roller follower 166b for a cam 166c on the shaft 9b. While the code bars are being set, the bail 165 serves to support the combination bars 75

4 against movement by their springs 4* so as to permit free movement of the code bars while they are being set under control of the keyboard. After the code bar setting operation, and just 5 prior to the operation of the actuating plates 23 and 24 by the cams 41 and 42 in the type-forming operation, the bail 165 is lowered to position the selected drive bars in driving relation to said plates. Subsequently after the printing operation 10 has been completed, the bail is raised to restore the active combination bars to normal or inactive position preparatory to the succeeding cycle.

Character selection.—Referring now to Fig. 17, 15 the standard arrangement of the keys of the keyboard 12, employed in the type-forming operation, requires that certain of the keys be assigned to two characters. As shown, seventeen of the keys are of this type and are thus dual in 20 character, there being in all forty-four keys including the space key but not including the various function keys. The present machine, however, has no provision for shifting the type to an upper case as in an ordinary typewriter, and 25 the printing of the different characters and symbols is therefore dependent in each instance upon the selection of a different character or symbol hole either in the main type pack 1^a or in the symbol pack 1^b. Under such circumstances, in 30 order to permit of the use of the standard keyboard with a single additional key mechanism corresponding to the ordinary case shift (duplicate case shift keys being provided in accordance with standard practice), it is necessary to employ 35 ten control bars 150 with ten corresponding code bars 5.

Of the ten control bars a group 150^a of six bars is arranged for operation selectively in different combinations under the sole control of any 40 of the forty-four character keys 113 and 113^a; a seventh control bar 150^b is arranged for operation by the case key 113^b in conjunction with said character keys; and a group of three control bars 150^c is arranged for operation by the three 45 font keys 113^c for the purpose of controlling in conjunction with the case key 113^b, the operation of the symbol forming pack 1^b.

Corresponding to the group of control bars 150^a is a group of six code bars 5^a, only three 50 of the control bars 150^a being shown in Fig. 16. Said bars are shiftable into different combinations to select any one of forty-four character holes in the main type pack 1^a. The use of six bars for this purpose is in accordance with the 55 well known permutational code whereby sixty-four different combinations are rendered available. Of these it is only necessary in the present instance to employ forty-four, one for each of the character keys 113, 113^a.

To select any one of the seventeen additional characters represented on the dual keys of the keyboard as "upper case" characters, the seventh bar 150^b is used in combination with the aforesaid six bars 150^a, thereby providing sixty-four 60 additional available combinations of which only seventeen are used, one for each of the seventeen dual keys. Thus by the depression of the case key 113^b in the usual manner, in conjunction with the depression of one of the seventeen dual keys, a seventh code bar 5^b is operated in combination with the six code bars 5^a to select the combination bar 4 of the character hole corresponding to the "upper case" of the depressed key.

75 *Symbol selection.*—The strips of the symbol

pack are operable in the present instance to form six different symbols under the control of the three control bars 150^c arranged for operation by three font keys 113^c both independently and in conjunction with the case key 113^b. 5 As above indicated, the printing of such symbols is for the purpose of identifying the upper and lower case characters in three different fonts, so that in the case of printing proof in connection with the perforation of control tapes to be 10 used in the control of typographic machines employing three different fonts of type, such printed proof will differentiate between the several fonts and also between upper and lower case characters therein. Accordingly, the symbol pack is provided, as above set forth, with six symbol holes, 15 three for the lower case and three for the upper case of each font. To form the three lower case symbols, the three font keys 113^c are operative to control the setting in different combinations of three control bars 150^c and their corresponding code bars 5^c. The arrangement is such that upon the depression of any of these three keys alone, the appropriate lower case hole of the symbol pack 1^b will be selected whereby to 20 effect the shifting of the strips of the symbol pack 1^b so as to carry the symbol facets 117^a into a particular relationship representative of a particular font and also of the lower case in said font. To form upper case symbols in either of 25 said fonts, the flag of the upper case key is adapted to cooperate with the flags of the three font keys to form three additional combinations each adapted to select a particular upper case hole in the symbol pack so as to form symbols representative of the upper case in the three different fonts. As herein shown, the three font keys respectively bear the legends "Roman," "Bold face" and "Italics."

It will be understood that in the operation of 40 the machine, a symbol is printed for each character. However, neither the case key 113^b nor any of the font keys 113^c is adapted to initiate an operating cycle of the machine. Accordingly, these keys have flags 117^a made shorter than the 45 flags 117 and having no connection with the clutch mechanism.

Miscellaneous key controlled mechanisms

In addition to the control bars 150 governing 50 character and symbol selection in the printing operation, there are as above indicated a plurality of control bars provided for the purpose of governing the operation of various mechanisms for controlling other operations of the machine. 55 Each of these mechanisms is under the control of one or more keys of the keyboard, of which there are seven in the present instance. Each key is operatively connected with one of the flags 117 in the manner hereinbefore described, and 60 similarly upon the depression of any such key its flag is shifted rearwardly and an operating cycle initiated by tripping the clutch 10. Also such shifting movement of each flag governs the operation of one or more control bars which, 65 through the operation of suitable means, effects a connection between the power driven mechanism and the part to be operated thereby. It should be observed, however, that in the present instance the various control bars governing the 70 machine functions other than type forming, are effective to perform their respective functions only when blocked against movement. Thus, when a given function is to be performed by a control bar, its flag is so notched as to prevent 75

movement of the bar. Conversely such control bar is, at other times, permitted to move and in such movement the aforesaid controlling function is not performed. This arrangement is employed in order that one control bar may be controlled by the operation of a plurality of key operated flags. Preferably, the flags of the various control keys are also notched so that upon the depression of any of such keys, the type-forming control bars 150^a will be set in a combination representing a space so as to insure that in the ensuing cycle no printing operation will occur.

Anvil blanking.—Means is provided so that at any time after the printing of a line has commenced, any anvil which has been moved to its number two position so as to be conditioned for operation into its number three position, may be retracted or "blanked." This mechanism is operative in the case of each of the anvils except in the case of the No. 0 or dummy anvil, and includes the rock shaft 103 and its bail 102 (Fig. 16) coacting with the tail pieces 101 of the anvil pawls 85 as above described. No such tail piece is provided in the case of the pawl for the No. 0 anvil, for in normal operation this anvil is not conditioned by the operation of an adjacent anvil, and since its pawl is automatically lifted in the operation of the No. 1 anvil, after the commencement of a line no blanking operation is necessary in the case of the No. 0 anvil.

The rock shaft 103 is actuated by power derived from the cam shaft 9 under the control of four keys, namely, a line key 167 (Fig. 17), a tabulating key 168, a blanking key 169, and a special paper feed key 183, each being operatively connected as above set forth, with one of the flags 117 arranged to govern the operation of one or more control bars. As shown in Fig. 16, 170 designates a control bar governed by the operation of any one of said four keys. When any of these keys is depressed their flags 117 act to block the bar 170 against movement by the operation of its spring 171 when the release bar is shifted as above set forth, said bar having a slot 172 therein operating in the same manner as the slots 156 for the control bars 150 as above set forth.

Interconnected with the control bar 170 is a bell crank 173 (Fig. 16) having a spring 174 which is relatively weak as compared to the leaf spring 171 and acts to hold the bell crank against a shoulder 174^a formed in the control bar. The bell crank 173 is in turn connected to the lower end of a link 175 slotted at its upper end to receive slidably a push rod 176 having its other end connected to an arm 177 of the double roller follower for a cam 178 on the section 9^b of the cam shaft 9.

When the bar 170 is blocked from movement, the push rod 176 is held by the link 175 in alignment with one end of a bar 179. The latter is suitably supported and guided for endwise movement and has its other end pivotally connected with an arm 180 on the rock shaft 103 carrying the blanking bail 102. In the event that none of the aforesaid four keys is depressed, the control bar 170 will be released for movement, with the result that just prior to the operation of the push rod 176 by the cam 178, said rod will be raised to an inactive position relative to the bar 179.

The line key 167 is, as its name implies, intended for operation to start a line; the tabulating key 168 is depressed when it is desired to

select an advanced position in the line; the blanking key is intended to be operated if for any reason it is desired to prevent printing at the point determined in the normal operation of the anvil advance mechanism as above described; 5 and the paper feed key is depressed when it is desired to advance the paper at some point in the line other than the beginning. When either of said keys is depressed, the push rod 176 is rendered effective in the manner aforesaid to operate the blanking bail 102.

Paper feed.—In the progression from one line to the next it is of course necessary to impart a feed movement to the paper A. As shown in Figs. 1 and 20, the paper A is in the form of a 15 web guided from a suitable source (not shown) at the rear of the machine by means of a wide flat tube 181 for passage upwardly in front of the printing head and thence between feed rollers 182 (Fig. 20) and 182^a. The latter is mounted 20 on a fixed rotatable shaft 182^b and the former on a yieldable shaft 182^c.

Feeding movement is accomplished either under the control of the line key 167 or of a special 25 paper-feed key 183 (Fig. 17). Each of these keys therefor is adapted through its flag 117 to govern the operation of a control bar 184 (Fig. 20) operative through the medium of a bell crank 185 and a link 186 to determine the position of a reciprocatory bar 187. The latter has one end 30 pivotally connected to a rocker member 188 loose on an extended end of the feed roller shaft 182^b and carrying a pawl 189 arranged for engagement with a ratchet wheel 190 fixed on said 35 shaft.

When the control bar 184 is blocked from movement, the bar 187 is supported by the link 186 in the path of movement of a bent arm 193 fast on a rock shaft 194 which is actuated by the follower 195 of a cam 196 on the cam shaft 9. On the other hand when neither of the aforesaid keys 167 and 183 is depressed, the control bar 184 is permitted to move to raise the link 186 against the action of a leaf spring 197 into a position out of the path of movement of said 45 arm 193. It will be observed that in this mechanism the latter arm constitutes in effect a push rod.

As above set forth, the paper feed key 183 is operative to control the anvil blanking mechanism so that in the cycle of operation initiated by such key, any anvil conditioned in the preceding cycle will be blanked and no printing will occur. Therefore, it will be understood that after the 55 paper feed operation has been completed it is necessary to condition the appropriate anvil to effect printing at the desired position in the line in the next character cycle. The means for effecting such conditioning operation may consist 60 of a manually operable device to be presently described under the heading "Tabulation."

No. 0 anvil advance.—In view of the fact that the anvil operating mechanism is of such character that the conditioning movement of any 65 anvil preparatory to the performance thereby of a printing operation is incidental to the actuation of an adjacent anvil, as above described, it is necessary to provide other means for conditioning the No. 0 anvil. This is accomplished in the present instance either under the control of the line key 167 or of a special key 199 (Fig. 17) termed the No. 0 anvil key. The latter is adapted for use when it is not desirable to oper- 75

ate the end of line key as, for example, when it is desired to start a line without paper feed.

The flags 117 of said keys 167 and 199 are so constructed that when either of these keys is depressed, the control bar 170 (Fig. 16) governing the operation of the anvil blanking mechanism is blocked against movement so as to cause the cam actuated push rod 176 to rock the bail 102 so as to lift all of the anvil pawls 85 except that for the No. 0 anvil. In addition each of the flags of said keys 167 and 199 is adapted to govern the operation of a control bar 200 (Fig. 19) operative through the medium of a bell crank 201 and a link 202 to control the position of one end of a draw bar 203 connected at its opposite end to a crank arm 204 on the blancker rock shaft 103. Adjacent its point of support by the link 202, the control bar 203 has a notch 205 in its upper edge providing a shoulder for engagement with the lower end of the lever 86 which, as hereinbefore described, is connected with No. 0 anvil. When the control bar 200 is blocked against movement by the depression of either the end of line key 167 or the No. 0 anvil key 199, the link 202 acts to hold the draw bar 203 in raised position. In the ensuing cycle of the cam shaft 9, the cam 178 thereon first operates to cause actuation of the blancker rock shaft 103 so as to operate the draw bar 203. The lever 86 is thus actuated to move the No. 0 anvil into its number two position so as to be engageable by its dog 8 of the advancing printing bar. Accordingly, in this cycle of operation initiated by the No. 0 or end of line key, the No. 0 anvil is advanced first into its number two position and then into its number three position, and as an incident to the latter movement will condition the number one anvil as above set forth. The idle or inactive stroke of the control bar 200 occurs against the action of a relatively light spring 206 acting upon the link 202.

Tabulating.—By reason of the character of the means provided for governing the operation of the anvils, it is possible to select one of various character positions in a line for the purpose of facilitating the arrangement of printed matter in tabular form. This is accomplished by advancing the appropriate anvil selectively according to the position in the line at which it is desired to start printing, all other anvils having first been rendered ineffective. I have provided means whereby such advance of any desired anvil may be accomplished manually, and also means operating under the control of the keyboard for effecting the selection successively of predetermined columnar positions.

The manually operable means for selectively conditioning any of the anvils for operation comprises in the present embodiment a hand lever 207 (Figs. 2 and 10) mounted for pivotal and sliding movement, the latter in a direction longitudinally of the printing head, for the purpose of establishing operative association with any one of the anvils as may be desired. As herein shown, the lever 207 is slidably and pivotally supported upon the rear edge of the frame plate 55 (Fig. 10) overlying the anvils. For this purpose the plate is provided with a rearwardly projecting rounded rib 208 and the lever has a rounded socket 209 for receiving the rib. Depending from the lever is a finger 210 engageable with a shoulder 211 formed in the upper edge of each of the anvils 3. Projecting forwardly from the lever is a finger or pointer 212

terminating adjacent the convertible type 2 of the printing head.

It will be seen that by sliding the lever 207 lengthwise of the printing head to the desired character position, as indicated by the pointer 212, and then drawing the lever forwardly, any one of the anvils may be moved into its number two position so as to be conditioned for printing in the next operating cycle. Preferably the lever 207 has an arm 213 adapted to cooperate with a slotted plate 214 carried by the frame member 55, the slots being positioned with respect to the various anvils so as to insure engagement of the anvil operating finger 210 with the desired anvil.

For the selection of different positions in the line under the control of the keyboard, I provide means operating in the present instance to select successively certain character positions at predetermined spaced points in the line, in response to successive operations of the tabulating key 168. For this purpose a series of notched combination bars 216 (Figs. 10 and 19) are associated with the respective anvils 3, there being one combination bar for each anvil. The bars 216 (hereinafter termed tabulating bars) are suitably supported and guided in laterally spaced relation upon the frame member 55. For this purpose, the latter has a slotted guide plate 217 secured to its forward edge, and on the top of the frame member 55 is a guide plate 217¹ grooved to receive the bars 216. Each of said bars abuts at its rear end the depending portion 60 of one of the anvils, and its front end is acted upon by a leaf spring 218 constantly urging it rearward, and of a strength such as to be capable of imparting movement to the anvils against the action of their springs 59. Because of the independent character of the tabulating bars they do not interfere with the advance of the anvils in the normal operation.

The tabulating bars are selectively released for movement by the setting in different combinations of a series of code bars 219 operating in ways provided in the top of the frame member 55 and notched along their upper edges for cooperation with the tabulating bars notched along their lower edges. These code bars may be controlled selectively in any suitable or preferred manner. One form of means herein shown is in the nature of a cam mechanism (Fig. 19) comprising a cam drum 220 having a series of cam disks 221 mounted in spaced relation axially of a shaft 222, there being one cam disk for each of the code bars 219, of which there are seven in the present instance.

The cam disks 221 are provided with lobes 223 and spaces 224 engageable with the ends of the code bars 219 yieldably held against the disks by leaf springs 219². Said lobes and spaces are relatively arranged so that in any given angular position of the cam drum the disks will be effective to set the code bars in different combinations.

In the present instance, the peripheral portions of the cam disks are divided into twelve equal portions each having a lobe or space, and the drum is adapted to be moved through twelve successive steps or one revolution for each line, to select twelve different columnar positions in such line. In each of said steps, the cam drum is adapted to present a different combination of lobes and spaces, the combination presented in the first position of the drum at the beginning of a given line being such as to position the code 75

bars for the release of the tabulating bar corresponding to the first of the twelve predetermined columnar positions. The combination presented in the next position of the drum similarly serves to select the next tabular column, and so on. After the first position in a given tabular column has been selected, the space key 113^a may be operated until the proper digit position in such column is reached in the normal operation of 10 the anvil advance mechanism.

The cam drum is advanced step by step under the control of the tabulating key 168 by means including a pawl and ratchet device actuated by power derived from the cam shaft 9. Said device comprises a ratchet wheel 225 (Fig. 19) fast on a shaft 226 connected by spiral gearing 227 with the drum shaft 222. Loose on the shaft 226 is an arm 228 carrying at one end a pawl 229 yieldably urged into engagement with the ratchet 20 wheel, and having its other end connected to an actuating bar 230 suitably supported and guided for endwise movement. Movement of the bar 230 to operate the device is effected by means of a push rod mechanism similar to those above 25 described. In this instance, it comprises a push rod 231 connected with the follower 232 of a cam 233 on the shaft 9, and positioned relative to the actuating bar 230 by a link 234 and bell crank 235 connected with a control bar 236. Upon the 30 depression of the tabulating key 168, its flag 111 blocks the control bar 236 against movement and thereby causes the push rod 231 to be positioned for engagement with the actuating bar 230.

Upon the setting of the code bars 219 in position 35 to release a selected tabulating bar 216, the latter is permitted to move in proper timed relation to the operating cycle by means of a bail bar 237 fast on a rock shaft 238. Said shaft carries an arm 239 with which is pivotally connected 40 an actuating bar 240 supported for endwise movement against the action of a restoring spring 241 which is of sufficient strength to effect the return movement of the tabulating bars against the action of their springs 218.

45 When the tabulating key is depressed, said bar 240 is actuated by a push rod 242 under the control of a control bar 243 arranged to be blocked against movement by the flag 117 of the tabulating key. Like other push rod mechanisms, 50 the rod 242 is connected to the double roller follower 244 of a cam 245 on the cam shaft 9, and is positioned relative to the actuating bar 240 by a link 246 connected by a bell crank 247 to the control bar 243.

55 *Shift for anvil advance.*—The means provided for shifting the rack bars 110 and 111 to control under the operation of the keyboard, the direction of progression of the printing operation, comprises two push rod mechanisms (Fig. 15).

60 Both of said mechanisms are actuated by a cam 250 on the main actuating shaft 9, but are individually controlled by two control bars 251 and 252 in response to the operation of two keys 253 and 254, one of which is hereinafter termed 65 the forward key and the other the reverse key.

The control bars 251 and 252 are so constructed 70 as to be blocked by their respective flags 117 upon the depression of the corresponding keys 253 and 254. When the control bar 251 is so blocked it operates through the medium of a bell crank 255 and a link 256 to position one end of a cam actuated push rod 257 in alignment with the lower rack bar 111; and when the control bar 252 is blocked, it operates through the 75 medium of a bell crank 258 and a link 259 to

position one end of a push rod 260 in alignment with the upper rack bar 110. Said push rods are respectively connected at their opposite ends to an arm 261 fast on a rock shaft 263 also having rigid therewith the double roller follower 264 of 5 the cam 250.

When the anvil arms 11 are in the position occupied for effecting progression of the printing operation in the normal direction from left to right, the rack bars 110 and 111 are in the 10 relation shown in Fig. 11. Assuming that the reverse key 254 has been depressed so as to position the push rod 260 in alignment with the upper rack bar 110, in the ensuing cycle, the plate 89 carrying the rear ends of the anvil arms 11 15 is shifted to the right in said figure thereby carrying said arms into the position shown in broken lines in Fig. 11. Similarly the lower rack bar 111 is actuated under the control of the advance key 253 to restore the parts to their normal relation, with the plate 89 shifted to the left, as shown in full lines in Fig. 11. It will of course be understood that as in the case of the other push rod mechanisms hereinbefore described, when neither of the keys 253 or 254 are 20 depressed, the push rods 257 and 260 are moved into their inactive positions.

In order to prevent simultaneous operation of the rack bars 110 and 111 and thereby avoid possible injury to the mechanism, the flags 117 30 corresponding to the two keys 253 and 254 are preferably interconnected by means of a lever 265 (Figs. 15 and 17) pivotally supported intermediate its ends on a suitable fixed pivot.

As above set forth, the flags 117 of the control 35 keys may be so notched that in addition to controlling their appropriate control bars they will also control the operation of the type-forming mechanism for the purpose of shifting the type facets into the space or blank formation whereby 40 to render the printing anvils ineffective when operated into their No. 3 positions. This is particularly important in connection with the shift for changing the direction of progression of the printing operation. Normally the occasion for 45 changing the direction of progression of the anvils 3 arises upon the occurrence of an error. Assuming that the operator discovers that the wrong character has been printed and, desiring to reverse the direction of progression for 50 purposes of back spacing, depresses the reverse key 254. In the preceding cycle the next adjacent anvil (to the right) was advanced to its No. 2 position. Accordingly, in the cycle initiated for the depression of the reverse key, such conditioned anvil will be advanced to its No. 3 or printing position. To render this latter anvil ineffective, the flag of the reverse key is so constructed 55 as to cause the strips 113 of the type pack 1^a to be shifted into the space or blank formation. 60

Key locking devices

In some instances it is desirable to lock certain of the keys depressed subject to control by another key. Thus the case key 113^b, for example, 65 is preferably provided with means of a well known character and therefore not herein shown for holding it depressed. This means is under the control of the usual locking key 269.

In the case of the three font keys 113^c, a special 70 interlocking mechanism is employed (see Fig. 18). It comprises two levers 270 and 271, the former pivoted between its ends on a fixed bracket 272, and the latter pivotally supported between its ends by one end of the lever 271. The other end 75

of said lever engages in a slot 273 in the stem 114 of the "Roman" key; and the ends of the lever 271 respectively engage in slots 274 and 275 in the stems of the Bold Face and Italics keys. Leaf springs 276, 277 and 278 are arranged to bear respectively in vertically spaced notches 279 cut in the edges of each of the key stems.

By this construction and arrangement, when a key is depressed it will be held depressed by its leaf spring, the "Roman" key being shown in such position. If either of the other two keys had previously been depressed, they will be raised in the depression of the "Roman" key, through the operation of levers 270 and 271. Similarly depression of the "Bold face" key or "Italics" key, with either of the other two keys depressed, will result in their elevation by the action of said levers.

DUPLICATE PRINTING

20 As shown in Fig. 21, a plurality of duplicate records may be made simultaneously under the control of a single keyboard. In said figure I have shown a plurality of units *a*, *b*, and *c*. Unit *a* is in all respects similar to the machine above described except that the printing head is extended laterally into association with units *b* and *c* and the control bars governed by the key flags are also extended laterally for association with the latter two units. Also the section 9^b of the 25 cam shaft, and rock shafts 103, 238, are extended, the arrangement being such that the keyboard 12 of unit *a*, in addition to controlling successive operating cycles of this unit, causes units *b* and *c* to operate simultaneously and in the same manner as unit *a*, the only difference being that the control bars governed by the operation of the keyboard 12 of unit *a* also govern the operation of units *b* and *c*.

OPERATION

40 The operation of the machine will now be described, it being assumed that the machine is adapted to print characters and symbols, the latter for the purpose of identifying different fonts and upper and lower cases in such fonts. Also it 45 may be assumed that the direction of progression of the printing operation is normally from left to right and that the printing is to commence at the beginning of a line first with an initial upper case Roman letter, followed by lower case characters in the same font.

To condition the machine for the commencement of a line, the operator depresses the line key 167 with a resulting rearward shifting movement of its flag 117. In such movement, the control bar 170 (Fig. 16) is blocked for movement for the purpose of retaining the cam-actuated push rod 176 in active relation to the bar 179 for actuating the bail 102 and thereby lifting the pawls 85 of the various anvils 3. At the same time, control bar 200 (Fig. 19) is operated to hold draw bar 203, connected with the pawl blanking rock shaft 103, into engagement with the lever 86 which is connected with the No. 0 anvil. In addition said flag serves to block control bar 184 (Fig. 20) to retain the actuating bar 187 of the paper feed ratchet mechanism in active position relative to the arm 193 operatively associated with cam 196 on the cam shaft section 9^b.

At the end of the rearward shifting movement 70 of the flag 117 thus operated by the line key, an operating cycle of the cam shaft 9 is initiated. In this operation, the latch-tripping bail 120 (Fig. 15) is engaged by the segment 119 associated with the line key flag, the lug 132 of the segment passing through its notch 131 in the lock-

ing bar 130. The result is that the shaft 122 is rocked in a direction to raise the rear end of the arm 123, thus disengaging the spring pawl 124 from the lever 128. Thereupon, the lever is actuated by its spring 127 to shift the release bar 5 128 and the locking bar 130.

The locking bar 130, due to its shifting movement, prevents operation of other keys by reason of the fact that the notches 131 have been moved out of registration with the lugs 132 of the segments 119; and the release bar in its operation moves to position its notches 156 and 172 into alignment with the ends of the various control bars so as to permit movement of the latter unless the same are blocked from movement by operation of any of the key flags. In this particular instance as above indicated, the control bars 170, 200 and 184 are blocked while other control bars are permitted to move.

In the final movement of the release bar 128, 20 the clutch detent bar 139 (Fig. 15) is drawn downwardly out of blocking relation to the finger 138 of the friction clutch 18. When this occurs the cam shaft 9 commences a cycle of operation.

In such cycle, the cam actuated push rod 176 (Fig. 16) being in active position, engages the actuating bar 179 and rocks the shaft 103 to move the blanking bail 102 rearwardly thereby lifting all of the pawls 85 with the exception of the 30 pawl for the No. 0 anvil, so as to position the notches 94 therein for the reception of the rear ends of the anvil shanks 53, the anvils being in this operation actuated by the springs 59.

While the anvils 3 are thus being restored to 35 their initial or No. 1 positions in the operation of the blanking bail 102, the No. 0 anvil is advanced to its No. 2 position. This is accomplished by the draw bar 203 connected with the rock shaft 103, the draw bar having been positioned 40 for engagement with the lever 86 which is thus operated by the rock shaft to shift the No. 0 anvil into its No. 2 position.

A further operation performed in the cycle thus initiated by the line key is the advance of the 45 paper sheet A to position it for the line to be printed. In this operation, the actuating bar 187 (Fig. 20) of the paper feed ratchet mechanism, having been positioned by the blocking of the control bar 184 in the path of the arm 193, is 50 actuated by the cam 196.

Immediately following the movement of the No. 0 anvil into its No. 2 position as above set forth, the printing bar 7, moving rearwardly by the operation of cams 83 and 83^a and the slide 55 bars 79 (Fig. 2), causes the advance of the No. 0 anvil into its No. 3 position, and consequently the movement of the No. 1 anvil into its No. 2 position. In this operation the dog 8 of the printing bar corresponding to the No. 0 anvil, 60 engages with the notch 66 thereof formed in the rear end of the shank 53.

In the movement of the No. 0 anvil from the No. 2 to the No. 3 position, the shoulder 91 on the shank of the No. 0 anvil engages the lug 80 65 of the arm 11 of the No. 1 anvil, moving it into its No. 2 position; and in the latter movement, the cam 97 (Fig. 10) on the arm 11 of the No. 1 anvil engages the pawl of the No. 0 anvil to lift it in preparation for the return to its No. 1 70 position of the No. 0 anvil. Near the end of such return movement the No. 0 anvil is released from the dog 8 through the coaction of cam surfaces 99 and 100.

The cycle thus initiated by the line key 167 is 75

terminated by the restoration of the clutch detent bar 139 into position to block the clutch finger 138. This is accomplished by the cam 143 on the cam shaft section 9^a (Fig. 15), operating to swing the bell crank 147 into engagement with the lever 126 connected with the release bar 128 and the locking bar 130, the former being connected with the clutch detent bar 139. Assuming that the line key has not been held depressed by the operator, such movement of the lever 126 serves to effect reengagement thereof with the spring pawl 124 of the trip-off latch. Preliminary to such operation the rock shaft 161 with its bail 160 has been operated to restore the control bars and thereby free the release bar for movement. The timing of this operation will be described in connection with the first character cycle.

Assuming that the first character to be printed is the upper case roman letter C, the "Roman" font key 113^c and the case key 113^b will first be held depressed, and thereupon the "C" character key. The flags of the case and font keys, not being connected with the clutch mechanism, do not initiate an operating cycle. The character key however, is connected with the clutch mechanism and therefore its depression initiates an operating cycle by tripping the clutch 10 in the manner above set forth in connection with the line key.

In the selecting operation, the character key controls the setting in a predetermined combination of the group of six control bars 150^a and the corresponding code bars 5^a; the case key determines the operation of the seventh control bar 150^b and its corresponding code bar 5^b; and the font key determines the setting of the three control bars 150^c and the corresponding code bars 5^c.

The six code bars 5^a are thus set in a combination operative to select the combination bar 4 controlling the drive bars 15^a of the strip shifting device of the "C" hole in the main type pack. The seventh code bar 5^b, together with the font code bars 5^c, in turn control the selection of the combination bar for the drive bars of the particular symbol hole in the pack 1^b which corresponds to the symbol representing upper case roman. Movement of the control bars in the proper combination is transmitted to the code bars by means of the bell cranks 153 (Fig. 16).

During the shifting of the code bars 5, the combination bars 4 are held in raised position permitting free movement of the code bars, by means of the bail 165; and after the commencement of the operating cycle incident to the depression of the character key, the cam shaft 9 commences its cycle of operation. The bail 165 (Fig. 16) is actuated by its cam 168^c and bell crank 166 to permit downward movement of the selected combination bars 4, one for the "C" hole of the main type pack 1^a, and one for the proper symbol hole of the auxiliary type pack 1^b.

The cams 41 and 42 on the cam shaft section 9^a now operate to reciprocate the actuating plates 23, 24 of the printing head, whereupon the two sets of drive bars which have been selected are engaged by the shoulders 29 and 30 of the actuating plates coacting with the surfaces 33 and 34 on the drive bars, with the result that the strips 13 of the main pack and the strips 13^a of the sub-pack are shifted to form the appropriate type. Thus the selected character is formed in all character positions throughout the length of the main pack, and the proper identi-

fying symbol representative of upper case roman is formed in all character positions along the length of the sub-pack.

The character thus formed on the main type pack and the symbol formed on the sub-pack are printed in the first position in the line by the operation of the printing bar acting to advance the No. 1 anvil into its No. 3 position. In this connection, it will be remembered that the No. 1 anvil was, in the preceding cycle initiated by the line key, advanced to its No. 2 position. Therefore, in this first character cycle, after the formation of the character and symbol, the printing bar moves rearwardly and in such movement its dog 8 corresponding to the No. 1 anvil engages the notch 66 in the rear end of the shank 53, and as the printing bar completes its rearward stroke the No. 1 anvil is advanced to its No. 3 or printing position. At the same time the No. 2 anvil is shifted into its No. 2 position by the engagement of the shoulder 91 on the shank of the No. 1 anvil with the lug 90 on the arm 11 of the No. 2 anvil, in the manner above set forth, thus conditioning the No. 2 anvil for operation in the succeeding cycle. At the end of the return stroke of the printing bar 7, the No. 1 anvil is restored to its initial position in the manner above described for the No. 0 anvil.

After the selection of the combination bars 4 controlling the operation of the type packs 1^a and 1^b in the type-forming operation, the rock shaft 161 (Fig. 15) is operated through the medium of its connection with the cam shaft section 9^a to restore the control bars which have been permitted to move as a result of the depression of such key. Such restoration of the control bars occurs prior to the return movement of the selected combination bars by the operation of the bail 165, preparatory to the actuation of the release bar 128 by the cam 143, bell crank 147, and lever 126.

Notwithstanding the fact that the selected combination bars remain in their selected or lowered positions (Fig. 16), such restoration of the control bars is possible because of the character of the means employed for shifting the code bars as determined by the setting of the control bars. Thus in the restoring movement of the control bars, the arms 155 of the bell cranks 153 are free to move away from their shoulders 155^a. Following such restoring operation, the bail 160 moves reversely away from the shoulders 162 formed in the upper edges of the control bars or into position to permit movement of the control bars in the succeeding operating cycle.

Before the control bars have been fully reset in the restoring operation above described, the cam 143 (Fig. 15) operates the bell crank 147 so as to swing the lever 126 so as to return the release bar 128 and the locking bar 130 and to restore said lever 126 into engagement with the spring pawl 124 of the clutch trip-off latch device.

Near the end of the return stroke of the printing bar, the bail 165 is operated by its cam 166^c to restore the combination bars 4 to their initial positions. Upon such return of the latter, the code bars 5 are released for movement by the springs 155^b, acting on the lower bell crank arms 154, the code bars coming to rest when said arms 154 engage their shoulders 155^a of the control bars previously restored in the operation of the bail 160.

Assuming that in the succeeding cycle the character to be printed is the lower case roman letter *a*, the operation is substantially similar to that above described with the exception that the case key flag is not shifted. Thus in this instance, the depression of the character key causes the six code bars 5^a to be set in a combination such as to select the combination bar corresponding to the letter *a* to be printed by the main pack; and the roman font key, being locked in its depressed position, causes the code bars 5^c to be set in a combination such as to effect the selection of the combination bar corresponding to the lower case roman symbol so that the sub-pack will be operated to form the symbol representing lower case roman.

Upon the depression of a dual key in conjunction with the case key, as for example when it is desired to print the sign "&", the operation 20 is the same as for an upper case letter except that in this instance the case key flag cooperates with the "7" key flag to effect the setting of the seven control bars 150^a and 150^b and their corresponding code bars 5^a and 5^b to select in the main type pack a character hole representing the "&" sign.

Under some circumstances, it may be desirable to condition the machine for starting the printing 30 operation at the beginning of a line without effecting a paper feeding operation. This is accomplished by the depression of the No. 0 anvil advance key 199 whose flag 117 is operative to block control bar 170 (Fig. 16) thereby rendering the cam actuated push rod 176 effective to operate the blancker bail 102 for the purpose of restoring all of the anvils 3 to their initial or No. 1 positions. At the same time said flag 117 operates to block control bar 200 (Fig. 19) so as to retain the draw bar 203 in active relation to the lever 86 connected to No. 0 anvil, the draw bar being actuated in the rocking motion of the shaft 103 carrying the blancker bail 102. In other words, the operation in this instance is the same as occurs upon the depression of the line key except that the control bar 184 is in this instance not blocked by the flag 117 of the No. 0 anvil key, and accordingly the paper feed mechanism is not operated.

When it is desired to tabulate, any one of a plurality of columnar positions may be selected under the control of the keyboard, or if desired any position in the line may be selected by the manual operation of the lever 207. Upon the depression of the tabulating key 168, its flag 117 operates to block the control bar 170 thereby actuating the anvil blanking bail 102. The conditioning movement of the No. 0 anvil does not occur because said flag is not adapted to block the control bar 200 controlling the No. 0 anvil advance. However, it does block control bars 236 and 243 (Fig. 19), the former being thus rendered operative to hold the cam actuated push rod 231 in operative relation to the actuating bar 230 of the means for advancing the cam drum 220. Similarly, the control bar 243 renders operative the cam actuated push rod 242 to actuate the bar 240 for rocking the shaft 238 thereby positioning its bail 237 to permit movement of the selected tabulating bar 216.

With the initial depression of the tabulating key, the cam drum 220 is advanced one step resulting in the setting of the code bars 218 in a combination such as to release the tabulating 75 bar 216 corresponding to the first of the pre-

determined number of tabular columns; and upon successive operations of the key succeeding tabular columns are similarly selected. After the selection of a tabular column, a desired digit position in such column is effected by the depression of the space key 113^a to effect the progressive operation of the anvils while at the same time controlling the operation of the printing head so as to position the type facets of the main pack 1^a in space or blank formation. 10

Manual operation of the individual anvils by the lever 207 (Fig. 10) is effected by sliding the lever lengthwise of the printing head to the desired position, and then drawing it forwardly to advance a selected anvil to its No. 2 position. It 15 will of course be understood that such manual operation of a selected anvil into No. 2 position to condition it for engagement by the printing bar, may be utilized for other purposes than tabulating.

Preliminary to the operation of the hand lever 207, it may be desirable to restore all of the anvils to their initial or No. 1 positions. This may be accomplished by the depression of the special blanking key whose flag 117 serves only 25 to block control bar 170 controlling the operation of the blanking bail 102.

To effect a change from the normal direction of progression of the printing operation, the reverse key 254 is depressed resulting in the shifting 30 of its flag 117 which is so constructed as to block control bar 252 (Fig. 15). As a result, cam actuated push rod 260 is conditioned for engagement with the upper rack bar 110 thereby actuating the plate 89 from the full line position 35 shown in Fig. 11 to that shown in broken line in said figure. The result of this shifting movement of the plate 89 is to carry the forward ends of the anvil arms 11 from the full line positions shown in Fig. 14, to the broken line positions indicated therein. 40

The shifting operation takes place just prior to the movement of the next adjacent anvil to the right into its No. 3 position, having been advanced to its No. 2 position in the previous 45 cycle. Therefore, by the time said anvil is engaged for advance to the No. 3 position, the control arms are positioned to reverse the direction of progression of the anvils.

To render the anvil thus advanced to No. 3 50 position during the reversing cycle, ineffective to perform a printing operation, the flag 117 of the reverse key is so constructed as to control the setting of the control bars 150^a and thereby of the code bars 5^a so as to select the combination 55 bar 4 corresponding to the space or blank character. Thus, notwithstanding the advance of the aforesaid anvil into its No. 3 position, no character is printed.

To illustrate the operation more clearly, reference is made to Fig. 14 in which the three anvils illustrated are designated for convenience as Nos. 5, 6, and 7. Assuming that anvil No. 6 has been moved to its No. 3 position and that in such movement the printing of an erroneous 65 character has occurred, the operator, desiring to make a correction, depresses the reverse key 254, the No. 7 anvil having been conditioned by movement into its No. 2 position. In the ensuing cycle, initiated by the reverse key, the anvil arms 70 11 are first shifted to the positions shown in broken lines, whereupon the No. 7 anvil is moved to No. 3 position and the No. 6 anvil is advanced to its No. 2 position. Accordingly, in the next cycle, initiated by the depression of the proper 75

character key, the No. 6 anvil is moved into position to print the correct character and the No. 5 anvil advanced to its No. 2 position.

Similarly a change from progression in the 5 reverse direction to the normal progression is effected by the depression of the advance key 253, whose flag blocks control bar 251 and conditions the cam actuated push rod 257 for engagement with the lower rack bar 111. As before, the arms 11 are shifted, this time to the 10 full line positions shown in Fig. 14, whereupon the No. 5 anvil is advanced to its No. 3 position but without performing a printing operation, and anvil No. 6 is conditioned by movement 15 into its No. 2 position preparatory for the succeeding cycle.

This application is a continuation in part of my prior application Serial No. 466,991, filed July 10, 1930.

20 I claim as my invention:

1. In a printer of the character set forth, a convertible type composed of a multiplicity of delineating elements disposed in a common plane and freely movable varying distances in said 25 plane to form different characters, all of said elements coacting in different character formations.

2. A printer of the character set forth having a convertible type comprising a multiplicity of 30 elements having similarly shaped facets and mounted for free relative movement in a common plane, said facets being disposed in closely spaced relation but relatively offset in said plane to a greater or less degree according to the 35 contour of the character outline to be formed.

3. In a character-forming printer, a convertible type composed of a plurality of elements with similarly shaped facets disposed in a common plane, which elements are freely movable 40 along contiguous parallel paths in said plane to position the facets selectively in different combinations to form type faces respectively representing different characters.

4. A printer having a convertible type whose 45 face is composed of a plurality of similarly shaped elongated facets shiftable relative to each other into different character formations, the facets forming the top and bottom portions of the type being of greater length than the intermediate facets.

5. A printer having a convertible type whose 50 face is composed of a plurality of facets shiftable relative to each other into different character formations, said facets having the same 55 general contour but with certain of the facets relatively larger than the others.

6. A printer having a type pack providing a plurality of sets of type-forming elements, and 60 selectively operable means for converting all of said sets into any one of a plurality of different characters simultaneously.

7. A printer having a type pack composed of a plurality of metallic ribbon-like strips, guide means for said pack of strips permitting free movement between the strips, and a set of printing elements formed upon the edges of said strips and providing a plurality of facets relatively shiftable into different character-forming combinations.

70 8. A printer having a type pack comprising a plurality of thin strips with type-forming elements thereon and projecting from one face of the pack, guides between which said strips are movable to carry said elements into different character-forming combinations selectively, and

means for imparting endwise movement to said strips selectively to carry said elements varying distances in a common plane into different character forming combinations.

9. A printer having a type pack comprising a plurality of thin strips with type-forming elements formed thereon and projecting from one face of the pack, guides between which said strips are movable to carry said elements into different character-forming combinations selectively, and means for moving said strips selectively to carry said elements varying distances in a common plane into different character-forming combinations, said guides being spaced apart a distance slightly greater than the combined thickness of the strips to accommodate a film of lubricant between adjacent faces of the several strips.

10. A printer having a set of character-forming elements, carriers for the individual elements arranged in the form of a pack, and means operating upon said carriers selectively to shift said elements into different character-forming combinations with all of said elements coacting in the formation of different characters.

11. A printer having a set of character-forming elements, carriers for the individual elements arranged in the form of a pack and mounted to move said elements in a common plane, and selectively-controlled power-actuated means for moving said carriers relative to each other to position said elements in different character-forming combinations.

12. A printer having a set of character-forming elements, movable carriers for the individual elements, and selectively-controlled power-actuated means for moving said carriers to position said elements in different character-forming combinations but at all times in the same plane, said power-actuated means having a uniform motion for each character formation.

13. A printer having a set of character-forming elements providing a convertible type, carriers for the individual elements having a set of actuating surfaces adapted when arranged in a predetermined relation to position said elements in a certain character-forming combination, and actuating means for said carriers comprising a driven part adapted for coaction with said actuating surfaces to position said elements in said predetermined relation, and a constantly actuated reciprocatory driving part with which said driven part may be operatively associated selectively for movement therewith.

14. A printer having a set of character-forming elements, carriers for the individual elements mounted for individual endwise movement with said elements in closely spaced relation, said carriers having a plurality of sets of actuating surfaces, one set for each character to be formed and the surfaces of each set being differently disposed relative to each other according to the character corresponding thereto, and actuating means for said carriers comprising a device for each set of surfaces operable thereon to position said elements in a predetermined character-forming combination, and a common reciprocating driving part with which said devices may be operatively associated selectively to move said carriers.

15. A printer having a set of character-forming elements providing a convertible type, a plurality of relatively thin metallic strips arranged in the form of a pack and mounted for endwise movement in closely spaced parallel relation,

said strips constituting carriers for the individual character-forming elements and having a plurality of sets of actuating surfaces, one for each character to be formed with the surfaces 5 of each set differently disposed according to the character corresponding thereto, and actuating means for said strips comprising a device for each set of surfaces operable thereon to position said elements in a predetermined character-forming combination, and a common reciprocating driving part with which said devices may be operatively associated selectively to impart endwise movement to said strips.

16. A printer having a set of character-forming elements providing a convertible type, a plurality of relatively thin metallic strips arranged in the form of a pack and mounted for endwise movement in closely spaced parallel relation, said strips constituting carriers for the individual 10 character-forming elements and having a plurality of slots to form in the pack a character hole for each character to be formed with oppositely disposed shoulders positioned according to the corresponding character, and actuating 15 means for said strips including a plurality of driven parts one for each character hole and each comprising two oppositely movable bars adapted for coaction respectively with the opposed shoulders of one character hole, and a 20 pair of reciprocating actuators with which said bars are selectively engageable for movement in opposite directions into engagement with their corresponding shoulders on the strips.

17. A printer having a set of character-forming elements providing a convertible type, a plurality of thin metallic strips arranged in the form of a pack and individually movable endwise of the pack, said strips constituting carriers for the individual character-forming elements 25 and having a plurality of slots providing a character hole in the pack for each character to be formed with a set of shoulders formed at one end of each hole, a device entered in each of said holes for movement into engagement with the shoulders thereof so as to position them in alignment, and means for selectively actuating the devices in the several holes, said slots being positioned in the respective strips so that when the shoulders of any given hole are brought into 30 alignment the character corresponding to that hole will be formed by said elements.

18. A printer having a set of character-forming elements, carriers for the individual elements comprising thin flat plates arranged in the form 35 of a stack and adapted for individual endwise movement to position the elements in a predetermined character-forming combination, said carriers having said character-forming elements on one longitudinal edge thereof and also having a set of actuating surfaces adapted when positioned in a predetermined relation to cause said elements to form a character, and a device movable into engagement with said surfaces to position them in their said predetermined relation.

19. A printer having a set of character-forming elements, a plurality of relatively thin metallic strips arranged in the form of a pack and individually movable endwise, said strips constituting carriers for the individual character-forming elements and having a plurality of slots providing a character hole in the pack for each character to be formed with a set of shoulders formed at one end of each hole, a drive bar entered in each of said holes for movement into engagement with the shoulders thereof so as to

position them in alignment, said slots being positioned in the respective strips so that when the shoulders of any given hole are brought into alignment the character corresponding to that hole will be formed by said set of elements, a pair of actuator plates mounted on opposite sides of the pack for endwise movement relative thereto, and power means for reciprocating said plates, said drive bars being selectively movable into engagement with both of said plates for actuation thereby. 10

20. A printer having a set of character-forming elements, a plurality of metallic strips arranged in the form of a pack and individually movable endwise, said strips constituting carriers for the individual character-forming elements and having a plurality of slots providing a character hole in the pack for each character to be formed with a set of shoulders formed at one end of each hole, a drive bar entered in each of said holes for movement into engagement with the shoulders thereof so as to position them in alignment, said slots being positioned in the respective strips so that when the shoulders of any given hole are brought into alignment the character corresponding to that hole will be formed by said set of elements, a pair of actuator plates mounted on opposite sides of the pack for endwise movement relative thereto, and cam means for reciprocating said plates, said drive bars being selectively movable into engagement with both of said plates for actuation thereby. 15

21. A printer having a set of character-forming elements, a plurality of metallic strips arranged in the form of a pack and individually movable endwise, said strips constituting carriers for the individual character-forming elements and having a plurality of slots providing a character hole in the pack for each character to be formed with a set of shoulders formed at each 40 end of the hole, a pair of drive bars entered in each of said holes for movement into engagement with the shoulders thereof so as to position them in alignment, said slots being positioned in the respective strips so that when the shoulders of any given hole are brought into alignment the character corresponding to that hole will be formed by said set of elements, two pairs of actuator plates, and means for reciprocating said two pairs of plates in opposite directions, the 45 plates of each pair being disposed on opposite sides of the type pack but movable in the same direction, and the two drive bars of each pair being movable into engagement respectively with the oppositely moving pairs of actuator plates. 50

22. A printer having a set of character-forming elements, a plurality of metallic strips arranged in the form of a pack and individually movable endwise, said strips constituting carriers for the individual character-forming elements 60 and having a plurality of slots providing a character hole in the pack for each character to be formed with a set of shoulders formed at one end of the hole, a drive bar entered into each of said holes for movement into engagement with the shoulders thereof, said slots being positioned in the respective strips so that when the shoulders of any given hole are brought into alignment the character corresponding to that hole will be formed, an actuator plate mounted for movement 65 parallel to the pack and having a plurality of shoulders thereon one set for each character hole, and means for reciprocating said plate, each of said drive bars having an actuating surface movable into engagement with a shoulder on the 70

actuating plate whereby the drive bars may be moved selectively to align the shoulders of their respective character holes.

23. A printer having a set of character-forming elements, carriers for the individual elements providing a set of shoulders adapted when moved into a predetermined relation to shift said elements into a predetermined character-forming combination, a reciprocating actuator comprising a plate having a notch therein, and a bar having a notch therein normally permitting free reciprocation of said plate, said bar having adjacent its notch an actuating surface and being movable to position said surface within the notch in the actuator plate so as to render the latter effective to move the bar into engagement with the set of shoulders on said carriers for the purpose of positioning the latter in said predetermined character-forming combination.

24. A printer having a set of character-forming elements, carriers for the individual elements arranged in the form of a pack and providing a set of shoulders adapted when moved into a predetermined relation to shift said elements into a predetermined character-forming combination, a reciprocating actuator comprising a pair of plates disposed on opposite sides of the pack, and a drive bar disposed transversely of said two plates and movable first into interengaging relation therewith and then with the plates into engagement with said set of shoulders on the carriers to position the latter in said predetermined character-forming combination.

25. A printer having a set of character-forming elements, carriers for the individual elements arranged in the form of a pack and providing a set of shoulders adapted when moved into a predetermined relation to shift said elements into a predetermined character-forming combination, a reciprocating actuator comprising a pair of plates disposed on opposite sides of the pack, a drive bar disposed transversely of said two plates and movable first into interengaging relation therewith and then with the plates into engagement with said set of shoulders on the carriers to position the latter in said predetermined character-forming combination, and cam means for reciprocating said plates.

26. A printer having a convertible type face composed of a multiplicity of closely spaced similarly shaped facets, a constantly operating drive means, means actuated by said drive means for shifting said facets into different character-forming combinations, an ink-carrying medium, and impression means also actuated by said drive means in timed relation to said shifting means and operable to press said ink-carrying medium toward said type face.

27. A printer having a convertible type face composed of a multiplicity of closely spaced similarly shaped facets, means operable to shift said facets into different character-forming combinations selectively, an inked ribbon, and an impression element operable to press a writing medium against said type face with the ribbon interposed between the writing medium and the impression element.

28. A printer having a plurality of sets of character-forming elements, each set constituting a convertible type, means for shifting the various sets of elements into different character-forming combinations with all of the sets forming the same character simultaneously, and printing means including a series of pressure devices, one for each set of elements, said devices being oper-

able selectively to determine which of the various sets of elements is to be printed.

29. A printer having a set of type-forming elements for each character position in a line and a pressure element for each of said character positions, and means for arranging the various sets of type-forming elements in said line simultaneously into any one of a plurality of different character formations, said pressure elements being arranged in a straight row opposite said line and independently operable to determine the position in said line at which any one of said characters is to be printed.

30. A printer having means for presenting in a plurality of different positions in the same row a plurality of individually convertible type, selectively operable means for converting said type simultaneously so as to represent the same character and a plurality of impression elements one for each type and independently operable to determine the position at which the said character is to be printed, said elements being arranged in a row opposite said type.

31. A page printer having a plurality of type spaced apart according to the spacing of the characters to be printed in the line, a series of independently movable pressure elements one for each of said type, said pressure elements being arranged in a row conforming to said line to be printed, means for actuating said series of elements progressively to print a line, and means operable upon the printing of the last character in a given line to institute a second progressive operation for the next line.

32. A page printer having a plurality of convertible type spaced apart according to the spacing of the character to be printed in the line and simultaneously convertible into different character formations, a pressure element for each of said type, means for movably supporting said pressure elements in a straight row opposite the line to be printed, means for actuating the individual elements progressively, and means operable to render any one of said elements ineffective so as to provide a space between words or characters in a line.

33. A page printer having a plurality of convertible type spaced apart according to the spacing of the character to be printed in the line and simultaneously convertible into different character formations, a pressure element for each of said type, means for actuating the individual elements progressively, and means for controlling the operation of said elements to terminate a line.

34. A page printer having a plurality of convertible type spaced apart according to the spacing of the characters to be printed in the line and simultaneously convertible into different character formations, a pressure element for each of said type, means for actuating the individual elements progressively, means operable at any point in the progressive operation of the elements to terminate such operation, and means operating as an incident to the termination of one line to initiate another progressive actuation of the elements for a new line.

35. A page printer having a plurality of convertible type spaced apart according to the spacing of the characters to be printed in the line and simultaneously convertible into different character formations, a series of pressure elements one for each of said type, mechanism including a power actuator and a control means therefor for actuating said elements successively

- beginning with the first element of the series, and means operable upon said control means to terminate the line.
36. A page printer having a plurality of convertible type spaced apart according to the spacing of the characters to be printed in the line and simultaneously convertible into different character formations, a pressure element for each of said type, means supporting said elements for independent movement in a straight row opposite said line, actuating means for said elements, and means for controlling the operation of said pressure elements by said actuating means, said control means being operative in the case of any one element as an incident to the operation of the next preceding element whereby to effect the successive actuation of the elements.
37. A page printer having a plurality of individually convertible type spaced apart according to the spacing of the characters to be printed in a line and simultaneously convertible into different character formations, a pressure element for each of said type, means for supporting said elements for independent movement, a power driven actuator for the pressure elements, and means operable to render said actuator effective to operate said pressure elements in a predetermined order.
38. A page printer having a plurality of convertible type spaced apart according to the spacing of the characters to be printed in a line and simultaneously convertible into different character formations, a pressure element for each of said type, a power driven actuator for the pressure elements, control means operable to render said actuator effective to operate said pressure elements in progressive order, and means for governing the operation of said control means to terminate one line and as an incident thereto initiate a new line.
39. A page printer having a plurality of convertible type spaced apart according to the spacing of the characters to be printed in a line and simultaneously convertible into different character formations, a pressure element for each of said type, a power driven actuator for the pressure elements, and a progressively advancing control means operable to present said elements to said actuator successively.
40. A page printer having a plurality of convertible type spaced apart according to the spacing of the characters to be printed in a line and simultaneously convertible into different character formations, a pressure element for each of said type, a power driven actuator for the pressure elements, and a progressively advancing control means operable to present said elements to said actuator successively, said control means comprising a series of control elements respectively operable by adjacent pressure elements.
41. A printer having a type pack providing a plurality of type, power actuated printing mechanism including a plurality of impression elements one for each type, means for supporting said impression elements for independent movement, a mechanically driven actuator for said elements, control means normally operative to govern the operation of said elements by said actuator in progressive order, and means selectively operable to render ineffective the movement of one or more of said impression elements by said actuator.
42. A printer having a row of spaced type, a reciprocating actuator, a series of plungers, one for each of said type normally positioned out of the path of movement of the actuator, and a progressively actuated control means operable as an incident to the movement of one plunger by the actuator to move the next adjacent plunger of the series into the path of the actuator.
43. A printer having a row of spaced type, a series of plungers, one for each of said type, means for actuating said plungers including a series of reciprocable actuating elements one for each of said plungers, power driven means for reciprocating said elements, and a control mechanism operable to render said actuating elements effective as to their respective plungers in succession.
44. A printer having a convertible type composed of a plurality of contiguous delineating elements disposed at all times in a common plane, and selectively operable means for shifting said elements relative to each other in said plane to produce different character formations successively.
45. A printer having a convertible type composed of a plurality of contiguous elongated delineating elements disposed at all times in a common plane, and selectively operable means for shifting said elements parallel to each other in said plane to produce different character formations successively.
46. A page printer having a plurality of convertible type spaced apart according to the spacing of the characters in a line, each type being composed of a group of contiguous delineating elements disposed at all times in a common plane and mounted for relative shifting movement in said plane, and selectively operable means for causing the different groups of elements to be arranged simultaneously in any one of a plurality of different character formations.
47. A page printer having a plurality of convertible type spaced apart according to the spacing of the characters in a line, each type being composed of a group of contiguous delineating elements, and a plurality of carriers for said elements arranged in the form of a pack and each having a plurality of elements thereon, one for each of the groups spaced apart as determined by said spacing of the type.
48. A page printer having a plurality of convertible type spaced apart according to the spacing of the characters in a line, each type being composed of a group of contiguous delineating elements, a plurality of carriers for said elements arranged in the form of a pack and each having a plurality of elements thereon, one for each of the groups spaced apart as determined by said spacing of the type, and means for operating upon said carriers selectively to arrange the several groups of elements simultaneously in the same character formation.
49. A page printer having a plurality of convertible type spaced apart according to the spacing of the characters in a line, each type being composed of a group of contiguous delineating elements, a plurality of carriers for said elements arranged in the form of a pack and each having a plurality of elements thereon, one for each of the groups spaced apart as determined by said spacing of the type, means for operating upon said carriers selectively to arrange the several groups of elements simultaneously in the same character formation, and printing means including a series of impression elements, one for each type individually operable to determine the position in the line at which a character is to be printed.
50. A printer having a plurality of convertible

type, each composed of a group of contiguous delineating elements and mounted for shifting movement, and selectively operable means for causing different groups of elements to be arranged simultaneously in any one of a plurality of different character formations.

51. A printer having a plurality of convertible type, each composed of a group of contiguous delineating elements and mounted for shifting movement, selectively operable means for causing different groups of elements to be arranged simultaneously in any one of a plurality of different character formations, and printing means including a plurality of impression elements, one for each type and individually operable to determine the position at which a character is to be printed.

52. A printer having a convertible type face composed of facets disposed at all times in a common plane and relatively shiftable in said plane to form different characters, and means for shifting said facets operable to move some in one direction and some in the opposite direction.

53. A printer having a convertible type face composed of facets disposed at all times in a common plane and relatively shiftable in said plane to form different characters, and means for shifting said facets operable to move some in one direction and some in the opposite direction, said facets moving varying distances in one direction or the other according to the contour of the character formed thereby.

54. A printer having a convertible type face composed of facets disposed at all times in a common plane and relatively shiftable in said plane to form different characters, carriers for said facets, and selectively operable means acting upon said carriers to move them varying distances in successive character formations.

55. A printer having a convertible type face composed of facets disposed at all times in a common plane and relatively shiftable in said plane to form different characters, carriers for said facets, and key-controlled selectively operable means acting upon said carriers to move them varying distances in successive character formations.

56. A printer having a plurality of sets of character-forming elements, each set constituting a convertible type, means for shifting the various sets of elements into different character-forming combinations with all of the sets forming the same character simultaneously, and printing means including a series of progressively operable pressure devices, one for each set of elements.

57. A printer having a plurality of convertible type arranged in a row, selectively operable means for converting all of said type simultaneously into any one of a plurality of different character formations and operable to form different characters in succession, and printing mechanism operating in timed relation to the character forming means and proceeding from one character position to another in a line and from the end of one line to the beginning of another in substantially the same uniform progressive order.

58. In a printer having a row of convertible type, selectively operable means for converting the type into different character formations successively, and printing mechanism including impression means operative progressively in a straight line from one character position to an-

other, and a control means for said impression means operable to effect the printing of successive characters either in the same line or in successive lines in substantially the same progressive order.

59. The method of printing which consists in grouping a multiplicity of delineating elements in contiguous relation within a common plane with the adjacent elements freely movable relative to each other, shifting said elements varying distances in said plane to form different characters with all of the elements cooperating in the formation of different characters, and impressing writing and inking media against the characters as they are formed.

60. The method of forming type for printing letters, figures and like characters which consists in grouping a plurality of delineating elements in contiguous relation in a common plane with the adjacent elements freely movable relative to each other, and shifting said elements varying distances in said plane to form different characters with all of said elements cooperating in the formation of different characters.

61. The method of printing which consists in arranging a plurality of type faces convertible to form different characters in a single row and spaced apart according to the desired spacing of the characters in a line, converting all of said type faces in the row to form different characters in succession but with all of said type faces forming simultaneously the same character in said row upon each converting operation, and following each type-forming operation taking an impression of one only of the similarly formed characters in said row with the successive impressions proceeding progressively from one end of the row toward the other so as to print the different characters as formed in a line.

62. A printer having, in combination, a printing head having two type packs each providing a plurality of sets of elements shiftable relative to each other to form different characters, and means for shifting the elements of both packs simultaneously into different character forma-

63. A printer having, in combination, a printing head having a row of convertible type spaced apart in accordance with the spacing of the characters to be printed in a line, a second row of convertible type correspondingly spaced, each of said type comprising a plurality of delineating elements, and means for shifting said elements relative to each other to convert from one type formation to another.

64. A printer having a convertible type comprising a plurality of elements shiftable relative to each other into different character formations, selectively operable means for controlling the setting of said elements in various combinations to form different characters, and an auxiliary type also comprising a plurality of elements shiftable into different combinations, said selectively operable means including means for controlling the formation of the auxiliary type according to varying conditions accompanying the printing of characters by the first mentioned type.

65. A printer comprising, in combination, a type pack providing a plurality of sets of elements shiftable relative to each other to form different characters, and key-controlled means operable to convert all of said sets simultaneously into any one of a plurality of different character formations.

66. A printer having, in combination, a print-

- ing head, a main type pack providing a plurality of convertible type each comprising a set of type-forming elements, and an auxiliary type pack having a plurality of symbol forming type 5 and also composed of a plurality of forming elements, key controlled means for shifting the elements of the main type into different character forming combinations, said key controlled means including a special key operable in conjunction 10 with the character keys to control the setting of the elements of the auxiliary type into different symbol forming combinations.
67. A printer having, in combination, a printing head, a main type pack providing a plurality 15 of convertible type each comprising a set of type-forming elements, and an auxiliary type pack having a plurality of symbol forming type and also composed of a plurality of forming elements, key controlled means for shifting the elements 20 of the main type into different character forming combinations, said key controlled means including a plurality of special keys operable in conjunction with the character keys to control the setting of the elements of the auxiliary type into 25 different symbol forming combinations.
68. A printer having a printing head comprising a character type pack and a symbol type pack, each of said packs providing a plurality of sets of type forming elements, a plurality of dual 30 character keys and a case key, and means operable under the joint control of said dual keys and said case key to control the formation of characters and symbols by said two packs.
69. A printer having type-forming means comprising a plurality of convertible character type and a plurality of convertible symbol type, a key board having single and dual character keys, a case key and a font key, and means controllable by said dual keys jointly with said case and font 35 keys to govern the formation of characters and symbols by said type-forming means.
70. A printer having a type pack providing a plurality of sets of type-forming elements, an impression member for each set of elements, means 40 operable to shift said elements into different character formations, and means for actuating said impression members successively, said shifting means being operable to position said elements laterally out of the path of movement of said 45 members to render the latter ineffective to print.
71. A printer having a convertible type composed of a plurality of delineating elements shiftable into different combinations to represent different characters, an impression member operable upon the setting of said elements to form a 50 character to print the same upon a writing medium, a keyboard having a plurality of character keys including a space key, means controlled by said keys for shifting said elements into different combinations, said space key being operative to control the setting of said elements in inoperative relation to said impression member to render the latter ineffective to print.
72. A printer having convertible type each composed of a plurality of delineating elements shiftable in a common plane to form different characters in spaced character positions, and means for shifting said elements in said plane to arrange them either in different formations in said 55 character positions or in space or blank formation out of said character position.
73. A printer having convertible type each composed of a plurality of delineating elements shiftable in a common plane to form different characters in spaced character positions, and means 60 for shifting said elements in said plane to arrange them either in whole or in part in said character positions.
74. A printer having a keyboard comprising a plurality of character keys including a space key, type-forming means providing a plurality of convertible type each composed of a plurality of elements shiftable relative to each other, and means operative in response to the depression of said keys to selectively arrange the elements 65 of each of the type into different formations to form different characters including a space blank.
75. A type-writing machine comprising, in combination, type-forming means including a plurality of convertible type, and selectively operable mechanism for converting said type into different character formations successively, said mechanism comprising a plurality of code bars, key controlled means for governing the setting of said code bars in different combinations, and a plurality of combination bars one for each type 70 coacting with said code bars to govern the formation of successive characters.
76. A type-writing machine comprising, in combination, type-forming means including a plurality of convertible type and selectively operable mechanism for converting said type to form different characters successively, said mechanism comprising a plurality of keys each having a 75 codal element, a power driven mechanism, means operable by said codal elements for controlling said power driven mechanism to initiate successive operating cycles, a series of permutation elements adapted to be set in different combinations according to the character of said codal 80 elements, and a plurality of combination bars one for each type operable in accordance with the setting of said permutation elements to govern the formation of successive characters.
77. A type-writing machine comprising, in combination, type-forming means including a plurality of convertible type and selectively operable mechanism for converting said type to form different characters successively, said mechanism comprising a plurality of code bars, a plurality 85 of keys each having a codal element, a series of permutation elements controlled by said codal elements, means operable to transfer the setting of said permutation elements to said code bars, and a plurality of combination bars one for each 90 type coacting with said code bars to govern the formation of successive characters.
78. A type-writing machine comprising, in combination, type-forming means including a plurality of convertible type and selectively operable mechanism for converting said type to form different characters successively, said mechanism comprising a plurality of code bars, a plurality 95 of permutation elements adapted to be set in different combinations, means operable to transfer the setting of said permutation elements to said code bars, and a plurality of combination bars one for each type coacting with said code bars to govern the formation of successive characters.
79. In a character selecting mechanism, a keyboard having a plurality of dual character keys and a special key operable simultaneously with the character keys to select between the two characters, the combination of a code element 70 individual to each key and directly operable thereby, a series of movable control bars adapted to be selectively released in certain combinations under control of the code elements of the character keys alone and in other combinations under 75

control of the code elements of the character keys cooperating with the code element of the special key, the first mentioned combinations representing one of the characters of each character key and the second mentioned combinations representing the other characters of the character key, and means for blocking said control bars against movement while said code elements are being operated.

10. 80. In a character selecting mechanism, a keyboard having a plurality of dual character keys and a special key operable simultaneously with the character keys to select between the two characters designated thereby, the combination of a code element individual to each key and directly operable thereby, a series of control bars supported for movement transversely of said code elements, said bars being blocked against movement by the code elements of the character keys and released in particular combinations representing one of the characters of each key when said keys are actuated, a supplemental control bar supported for movement transversely of said code elements, said supplemental bar being blocked against movement by the code element of said special key and released when the key is operated to form, with the control bars released by the character keys, a combination representing the other characters designated by the character keys, and means selectively operated by said control bars in accordance with the combination in which they are released.

81. A type-writing machine comprising, in combination, type-forming means including a plurality of convertible type and selectively operable mechanism for converting said type to form different characters successively, said mechanism comprising a plurality of keys each having codal elements, a power driven means, means operable in response to the actuation of a key for controlling the power driven means to initiate successive operating cycles, a series of permutation elements adapted to be set in different combinations according to the character of said codal elements, a series of code bars, means for transferring the setting of said permutation elements to said code bars, and a plurality of combination bars one for each type coacting with said code bars to govern the formation of successive characters.

82. A type-writing machine comprising, in combination, type-forming means including a plurality of convertible type and selectively operable mechanism for converting said type to form different characters successively, said mechanism comprising a plurality of keys each having a codal element, a power driven means, means operable by said keys for controlling the power driven means to initiate successive operating cycles, a series of permutation elements adapted to be set in different combinations according to the character of said codal elements, a series of code bars, means for transferring the setting of said permutation elements to said code bars, and a plurality of combination bars one for each type coacting with said code bars to govern the formation of successive characters, each of said combination bars having an actuating spring, and means actuated by said power driven means for controlling the movement of said combination bars by said springs.

83. A type-writing machine comprising, in combination, type-forming means including a plurality of convertible type and selectively operable mechanism for converting said type to form

different characters successively, said mechanism comprising a plurality of keys each having a codal element, a power driven means, means operable by said keys for controlling the power driven means to initiate successive operating cycles, a series of permutation elements adapted to be set in different combinations according to the character of said codal elements, a series of code bars, means for transferring the setting of said permutation elements to said code bars, and a plurality of combination bars one for each type coacting with said code bars to govern the formation of successive characters, spring means for restoring said code bars, and means operable by said power driven means for restoring said permutation elements in advance of the restoration of said code bars, said transfer means being constructed to permit movement of the permutation elements in one direction independently of the code bars.

84. A type-writing machine comprising, in combination, type-forming means including a plurality of convertible type and selectively operable mechanism for converting said type to form different characters successively, said mechanism comprising a plurality of keys each having a codal element, a power driven means, means operable by said keys for controlling the power driven means to initiate successive operating cycles, a series of permutation elements adapted to be set in different combinations according to the character of said codal elements, a series of code bars, means for transferring the setting of said permutation elements to said code bars, a plurality of combination bars one for each type coacting with said code bars to govern the formation of successive characters, a release bar normally positioned to hold said permutation elements against movement and operative as an incident to the initiation of an operating cycle to release said permutation elements for movement, means for restoring said code bars, means operable by said power driven means for restoring said permutation elements in advance of the restoration of said code bars, and means operable upon such restoration of the permutation elements to restore said release bar, said transfer means being constructed to permit movement of the permutation elements in one direction independently of the code bars.

85. A type-writing machine comprising, in combination, type-forming means including a plurality of convertible type and selectively operable mechanism for converting said type into different character formations successively, said mechanism comprising a power driven shaft, a clutch controlling the operation of said shaft and having a control member, a detent for said member, a plurality of keys each having a codal element, means operable by said keys for actuating said clutch detent to initiate an operating cycle and including a release bar, a plurality of permutation elements controlled by said codal elements and adapted for movement upon the operation of said release bar, into different combinations according to the character of said codal elements, means operable under the control of said permutation elements to govern the formation of the successive characters, and means operable by said shaft in said cycle to restore said permutation elements and then said release bar to position said clutch detent in operative relation to said clutch control member for terminating said cycle.

86. A selective control mechanism comprising

- a power driven shaft having a clutch adapted to be tripped to initiate an operating cycle, a series of permutation elements and a series of code bars operatively associated therewith, key controlled means for effecting the setting of said permutation elements in different combinations with a corresponding setting of said code bars and also operative to trip said clutch to initiate an operating cycle of said shaft, said permutation elements being adapted for return movement independently of the code bars, a plurality of combination bars controlled by said code bars, and means actuated by said shaft to restore the permutation bars in advance of said code bars.
- 15 87. A selective control mechanism comprising a power driven shaft having a clutch adapted to be tripped to initiate an operating cycle, a series of permutation elements and a series of code bars operatively associated therewith, key-controlled means for effecting the setting of said permutation elements in different combinations with a corresponding setting of said code bars and also operative to trip said clutch to initiate an operating cycle of said shaft, a bail actuated by said shaft and operative first to restore said permutation elements and then to move out of engagement therewith, and a release bar operative by said shaft upon the restoration of said permutational elements to engage therewith to hold them against movement, said release bar being operative as an incident to the tripping of said clutch to release said permutation elements for movement.
- 30 88. In a keyboard controlled mechanism, a plurality of keys, a code element for each of said keys, a series of control bars adapted to be selectively operated under control of said code elements, means for holding said control bars in inoperative position independently of said code elements, power operated means operable in cycles for withdrawing said holding means to place the control bars under the control of said code elements, a member normally positioned in blocking relation to said power driven means to prevent its operation, means operated in response to the depression of any one of said keys for moving said member out of blocking relation to said power driven means to initiate the operation of said means through a single cycle, and means for returning said member to blocking relation to said power driven means to interrupt the operation thereof at the end of the cycle irrespective of the length of time the key is depressed.
- 45 89. In a keyboard controlled machine, in combination, a plurality of keys, a code element individual to each key for controlling a selecting operation, power driven means operable in cycles for effecting the selecting operation under control of said elements, a member normally positioned in blocking relation to said power driven means to prevent its operation, means operated by the depression of any one of said keys for moving said member out of blocking relation to said power driven means to initiate the operation of the means through a single cycle, and cam means operated by said power driven means for restoring said member to normal position to interrupt the operation of said power driven means on the completion of the operating cycle.
- 60 90. In a printer or the like, a character selecting mechanism, a keyboard having a plurality of manually operable keys, a code element individual to each of said keys and adapted to be operated by the actuation of the key, control bars selectively operable in different combinations by said code elements to control selective operations, a pivoted member operatively connected with each code element and adapted to be rocked about its pivot in response to the operation of a key and its associated code element, and a common member operable in response to the actuation of each of said keys and adapted to co-operate with said pivoted members to prevent the operation of more than one key at a time.
- 65 91. In a printer or the like, a character selecting mechanism, a keyboard having a plurality of manually operable keys, a code element individual to each key and operable thereby, control bars selectively controlled by said code bars to effect selective operations, a pivoted member operatively associated with each code element and adapted to be rocked about its pivot as an incident to the operation of a key and code element, a locking bar adapted to co-operate with said pivoted members to prevent the operation of more than one of said keys at a time, and means operated in response to the operation of any of said keys for shifting said locking bar into operative relation with said pivoted members.
- 70 92. In a character selecting mechanism, in combination, a group of control bars adapted to be released in different combinations to effect selective operations, a plurality of code elements supported for endwise movement of a predetermined extent transversely of said control bars, each of said code elements being operative to release a particular combination of control bars, a key individual to each code element for operating the element, a rocking member operatively connected with each code element and adapted to be rocked through a predetermined arc as an incident to the movement of the associated code element, and means coacting with said member for latching the code element in operated position.
- 75 93. In a selector mechanism, in combination, a code element adapted to control a selective operation, a key individual to the code element and operative to shift the element from a normal position, a pivoted member operatively associated with said code element and adapted to rock about its pivot as an incident to the shifting of the element, a locking bar having a slot normally positioned to provide a passage for said member when the latter is rocked about its pivot, and means for shifting said locking bar relative to said member after said member has been rocked out of normal position to withdraw said slot from the path of said member and thereby prevent the return of the member to normal position.
- 80 94. In a selector mechanism, in combination, a code element adapted to control a selective operation, a key individual to said element and operative when actuated to move the element into its active position, a pivoted bell crank member operatively connected at one end with said element and adapted to be rocked about its pivot by the movement of the element, a part carried by the free end of said member, a locking bar having a slot normally positioned to provide a passage for said part when said member is rocked about its pivot, means operated in response to the actuation of said key and effective after said part has passed through said slot for shifting said locking bar to move the slot out of the path of said part and thereby prevent return of the member to normal position, and means initiated in operation simultaneously with the shifting of said

locking bar for restoring the locking bar to normal position after a predetermined interval, said last means comprising a cam adapted to be operated through a complete cycle in response to the actuation of said key.

95. A printer having a row of convertible type simultaneously shiftable to form one of a plurality of different characters, a series of impression elements one for each type, and mechanism operable in successive cycles to convert said type and operate said impression elements progressively.

96. A printer having type-forming means including a plurality of convertible type simultaneously operable to form one of a plurality of different characters, a series of impression elements one for each type, means operable in successive cycles to convert said type and operate said impression elements successively, said means including a cam shaft, and a plurality of permutation elements for governing the operation of said type-forming means and controlling the operation of said cam shaft.

97. A printer having type-forming means including a plurality of convertible type simultaneously operable to form one of a plurality of different characters, a series of impression elements one for each type, means operable in successive cycles to convert said type and operate said impression elements successively, said means including a cam shaft, and key controlled mechanism for governing the operation of said type-forming means and controlling the operation of said cam shaft.

98. A printer having a type-forming means including a plurality of convertible type, a series of impression elements one for each type, power driven means for operating said type-forming means and said impression elements, a plurality of permutation elements, means operable to initiate the operation of said power driven means through a predetermined operating cycle and to control the setting of said permutation elements in a predetermined combination, and means controlled by said permutation elements to govern the operation of said type-forming means and said impression elements.

99. A printer having a type-forming means comprising a plurality of convertible type, a plurality of anvils movable toward and from said type, selectively operable means for governing the operation of said type-forming means to form any one of a plurality of different type simultaneously, a power driven shaft, a clutch controlling the operation of said shaft in successive cycles, a keyboard comprising a plurality of keys each having a codal element, means operable in response to certain of said keys for actuating said clutch to initiate an operating cycle, a plurality of permutation elements controlled by said codal elements, certain of said permutation elements being operable to govern said type-forming means, a printing bar reciprocable in the rotation of said shaft, means operable under the control of certain other of said permutation elements to condition one of said anvils for operation by said printing bar, and means operable as an incident to the movement of any one of said anvils by said printing bar to condition a next adjacent anvil for operation thereby in the succeeding cycle.

100. A printer having a row of convertible type simultaneously operable to form one of a plurality of different characters, impression mechanism for printing successively formed characters progressively, and means operable in successive cy-

cles to convert said type and operate said impression mechanism, said impression mechanism comprising a series of elements one for each type, a reciprocatory actuator having an operating member for each of said elements, and means rendering said operating members effective progressively in successive cycles.

101. A printer having a row of type, and a printing mechanism comprising a series of elements one for each type, a reciprocatory actuator having an operating member for each of said elements, and means operable as an incident to the actuation of one impression element to condition an adjacent element for movement by its operating member.

102. A printer having a row of convertible type simultaneously operable to form one of a plurality of different characters, impression mechanism for printing successively formed characters progressively, and means operable in successive cycles to convert said type and operate said impression mechanism, said impression mechanism comprising a series of impression anvils one for each type, a series of pawls operative to latch the respective anvils in a partially advanced position, and means engageable with said anvils to operate them only when in such partially advanced position.

103. A printer having a row of convertible type simultaneously operable to form one of a plurality of different characters, impression mechanism for printing successively formed characters progressively, and means operable in successive cycles to convert said type and operate said impression mechanism, said impression mechanism comprising a series of anvils arranged for reciprocation toward and from said type, latch means operative to hold said anvils in a partially advanced position, selectively operable means adapted to move said anvils to said partially advanced position, and means adapted to engage said anvils to move them only when in such advanced position.

104. A printer having a plurality of convertible type arranged in a row, means for converting said type to form simultaneously any one of a plurality of different characters, a series of impression elements one for each type, a reciprocatory actuator for said impression elements including a series of relatively movable operating devices, power driven means for actuating said type-forming means and said actuator in cycles, and means operative as an incident to the movement of one of said elements by its operating device in one cycle of said actuator to condition an adjacent element for operation by its device in a succeeding cycle of the actuator.

105. A printer having a row of convertible type simultaneously operable to form one of a plurality of different characters, impression mechanism for printing successively formed characters progressively, and means operable in successive cycles to convert said type and operate said impression mechanism, said impression mechanism comprising a series of impression elements one for each type, an actuator operating in successive cycles, and a control device for each of said elements operatively associated with an adjacent element, said control device being operative to condition its impression element for movement by said actuator as an incident to the operation by the actuator of the preceding impression element.

106. A printer having a row of convertible type simultaneously operable to form one of a

- plurality of different characters, impression mechanism for printing successively formed characters progressively, and means operable in successive cycles to convert said type and operate said impression mechanism, said impression mechanism comprising a series of pressure anvils one for each type, a reciprocatory actuator having a series of operating members engageable respectively with said anvils, and a member connected with each anvil and extending into operative association with an adjacent anvil for operation thereby, each member being adapted in such operation to impart a movement to its corresponding anvil to position it for engagement by its operating member.
107. A printer having a row of convertible type simultaneously operable to form one of a plurality of different characters, impression mechanism for printing successively formed characters progressively, and means operable in successive cycles to convert said type and operate said impression mechanism, said impression mechanism comprising a series of impression anvil one for each type, a reciprocatory actuator having a series of operating dogs pivotally mounted thereon, each of said anvils having a shoulder engageable by its corresponding dog upon movement of the anvil to a partially advanced position, and means for successively conditioning said anvils for engagement by their respective dogs in successive operating cycles.
108. A printer having a row of type arranged in spaced relation, an impression mechanism comprising a series of impression elements one for each type, an actuator having a series of operating members for the respective impression elements and arranged for operation in successive cycles, said impression elements being normally positioned out of operative relation to their respective operating members, means for conditioning a selected one of said impression elements for engagement by its operating member, means operative as an incident to the aforesaid movement of the last mentioned element to condition an adjacent element for engagement by its operating member in the succeeding cycle, and a latch member for each of said elements operative to retain it in such conditioned position.
109. A printer having convertible type arranged in spaced relation and operable simultaneously to form one of a plurality of different characters, impression mechanism, and means operable in successive cycles to convert said type and operate said impression mechanism, said impression mechanism comprising a series of anvils each having a normally retracted position spaced from said type, a reciprocatory actuator having an operating member for each of said anvils normally ineffective in the operation of the actuator, a latch device for each of said anvils, means operable to advance one of said anvils into operative association with its latch device so as to be held thereby in a partially advanced position adapted for engagement by its operating member, and means operative as an incident to the movement of said partially advanced anvil by the actuator to move an adjacent anvil into operative association with its latch device.
110. A printer having a row of type arranged in spaced relation, an impression mechanism, means operable in successive cycles to actuate said impression mechanism, said impression mechanism comprising a series of anvils each having a normally retracted position spaced from said

type, a reciprocatory actuator having an operating member for each of said anvils ineffective in the normal position of the anvils, a latch device for each of said anvils, means operable to advance one of said anvils into operative association with its latch device so as to be held thereby in a partially advanced position adapted for engagement by its operating member, means operative as an incident to the movement of said partially advanced anvil by the actuator to move an adjacent anvil into operative association with its latch device, said last mentioned means being also operative as an incident to the partial advance of the said last mentioned anvil to position the latch device of the first operated anvil to permit return movement of the latter to its initial position.

111. A printer having a row of type, an impression mechanism, and means operable in successive cycles to operate said impression mechanism, said mechanism comprising a series of anvils one for each type, a power actuated printing bar having a series of dogs one for each of the anvils, said anvils having a normally retracted position in which said dogs are ineffective in the movement of the printing bar to operate the anvils, a latch device for each of the anvils, and an arm individual to each of the anvils and extending into association with an adjacent anvil and its associated latch device, the arm of one anvil being operative by the associated anvil to condition the former for engagement by its dog in the operation of the printing bar, and being also operative to condition the latch device of such associated anvil to permit return movement thereof to its initial position upon the return of the printing bar to its initial position.

112. A printer having a row of convertible type simultaneously operable to form one of a plurality of different characters, impression mechanism for printing successively formed characters progressively, and means operable in successive cycles to convert said type and operate said impression mechanism, said impression mechanism comprising a series of impression elements one for each type, latch means operative to retain said elements in partially advanced position, means operative to engage an anvil when in such partially advanced position to move it toward said type, and cam means operable in the movement of one anvil to actuate the latch means of an adjacent anvil.

113. A printer having a row of convertible type simultaneously operable to form one of a plurality of different characters, impression mechanism for printing successively formed characters progressively, and means operable in successive cycles to convert said type and operate said impression mechanism, said impression mechanism comprising a series of anvils one for each of said type arranged for movement toward and from the type, a latch member operatively associated with each anvil and adapted to retain it in a partially advanced position, means for actuating said anvils operative thereon only when in such partially advanced position, and a cam member movable with each of said anvils and operative as an incident to the advancing movement of one anvil to position the latch member of an adjacent anvil into position to permit restoration of such adjacent anvil to its initial position.

114. A printer having a plurality of type, an impression mechanism comprising a series of impression elements one for each type, and a power

5 driven member, said mechanism comprising a plurality of control elements one for each of said impression elements adapted for individual movement in the normal operation of said impression mechanism, a restoring bail for said control elements, and key controlled means for operatively connecting said bail with said member.

10 115. A printer having a row of convertible type simultaneously operable to form one of a plurality of different characters, impression mechanism for printing successively formed characters progressively, and means operable in successive cycles to convert said type and operate said impression mechanism, said impression mechanism comprising a plurality of anvils one for each type and each having a latch member, a printing bar operative in successive cycles to move said anvils toward said type successively, said latch members being operative to render said printing bar effective as to its corresponding anvil, and means for operating said latch members to render such printing bar ineffective as to any of said anvils.

15 116. A printer having a row of convertible type simultaneously operable to form one of a plurality of different characters, impression mechanism for printing successively formed characters progressively, and means operable in successive cycles to convert said type and operate said impression mechanism, said mechanism comprising a series of anvils one for each type, a printing bar operable toward and from said type, said anvils having a normal retracted position in which said printing bar is ineffective to move them, a series of latch members one for each anvil and operative to retain the anvils in partially advanced position for actuation by said printing bar, means operative as an incident to the movement of one anvil by the printing bar to render the latch member of an adjacent anvil effective to retain it in condition for engagement on the succeeding cycle of the printing bar, and means common to said latch members for operating them to permit restoration of all of the 20 anvils.

25 117. A printer having a plurality of type and an impression mechanism comprising a series of impression elements one for each type and a power driven member, said mechanism comprising a plurality of control elements one for each of said impression elements adapted for individual movement in the normal operation of said impression mechanism, a restoring bail for said control elements, and key controlled means for operatively connecting said bail with said power member, said key controlled means comprising a keyboard having a plurality of function keys, a part to be operated connected with said bail, and means controlled by one or more function keys 30 to establish an operative relation between said power driven member and said part to be operated.

35 118. A printer comprising, in combination, a series of convertible type simultaneously operable to form one of a plurality of different characters, a series of impression elements one for each type, actuating means for said impression elements adapted to operate them progressively, selectively operable means for converting said type to form different characters successively between successive operations of said impression elements, said means for effecting the progressive operation of said elements including a series of control members respectively connected with the individual impression elements and normally associated with

40 elements adjacent thereto in one direction, and means for shifting said control members into association with the elements next adjacent thereto in the opposite direction to effect a change in the direction of progression of the printing operation.

45 119. A printer comprising a plurality of convertible type, a series of impression elements one for each type, means for operating said impression elements progressively in successive cycles, each of said elements having a control member normally associated with an impression element adjacent thereto in one direction for operation thereby and active in successive cycles to cause said elements to be operated progressively in one direction, and means for shifting said members into association with impression elements adjacent thereto in the opposite direction to effect a change in the direction of progression of the printing operation.

50 120. A printer having a plurality of convertible type, a series of impression elements one for each type each having a control member pivotally connected therewith, a power driven actuator operable in successive cycles and having an operating member for each of said impression elements normally in inactive relation thereto, and means for conditioning one of said elements for engagement by its operating member, each of said elements being adapted when operated in one cycle of said actuator to engage the control member of an adjacent element to condition the latter for operation in a succeeding cycle, and means for shifting said control members from association with elements adjacent thereto in one direction into association thereto with elements adjacent thereto in the other direction, said control members being operative in accordance with their positions to determine the direction of progression of the printing operation.

55 121. A printer having a plurality of convertible type, selectively operable means to convert said type simultaneously to form one of a plurality of different characters, a series of impression elements one for each type, and means for controlling the operation of said impression elements to effect their movement toward said type progressively in successive operating cycles, said means including a plurality of control members each pivotally connected with one of said impression elements, a carrier common to said members, and means for shifting said carrier to control the direction of progression of the printing operation, the control members of the various elements being in one position of the carrier operatively associated with elements next adjacent thereto in one direction and in the other position of the carrier with elements adjacent thereto in the other direction.

60 122. A printer having a plurality of convertible type, selectively operable means to convert said type simultaneously to form one of a plurality of different characters, a series of impression elements one for each type, and means for controlling the operation of said impression elements to effect their movement toward said type progressively in successive operating cycles, said means including a plurality of control members each pivotally connected with one of said impression elements, a carrier common to said members, and selectively operable power actuated means for shifting said carrier to control the direction of progression of the printing operation, the control members of the various elements being in one position of the carrier operatively associated with

elements next adjacent thereto in one direction and in the other position of the carrier with elements adjacent thereto in the other direction.

123. A printer having, in combination, type-

- 6 forming means comprising a series of convertible type, a series of impression elements for said type, means for operating said impression elements successively in a progressive order, and means for controlling the direction of progression comprising a member arranged to occupy either of two positions according to the direction of progression desired, power driven means, key controlled means for initiating a cycle of operation of said power means and controlling the operation 10 of said type-forming means, and other key controlled means for rendering said power means effective to change the position of said member.

- 124. A printer having a plurality of convertible type, selectively operable means to convert said 20 type simultaneously to form one of a plurality of different characters, a series of impression elements one for each type, and means for controlling the operation of said impression elements to effect their movement toward said type progressively in successive operating cycles, said means including a plurality of control members one for each of said impression elements, a carrier common to said members, and power actuated key controlled means for shifting said carrier to control the direction of progression of the printing 25 operation, the control members of the various elements being in one position of the carrier operatively associated with elements next adjacent thereto in one direction and in the other position 30 of the carrier with elements adjacent thereto in the other direction.

- 125. A printer having, in combination, a plurality of convertible type, a series of impression elements one for each type, means for operating 35 said elements successively to print characters formed successively by said type, said means including a plurality of control members arranged to be supported in two different positions to govern the direction of progression of the printing 40 operation, a carrier for supporting said members in said two positions, a rotatable element eccentrically associated with said carrier, operating devices for said rotatable member to shift said carrier in opposite directions, and means for actuating said devices selectively.

- 126. A printer having, in combination, a plurality of convertible type, a series of impression elements one for each type, means for operating said elements successively to print characters 45 formed successively by said type, said means including a plurality of control members arranged to be supported in two different positions to govern the direction of progression of the printing operation, a carrier for supporting said members 50 in said two positions comprising a plate, a pair of shiftable supports for said plate, a pair of rack bars for operating said supports simultaneously, and means for selectively operating said rack bars to impart a shifting movement to said plate.

- 127. A printer having, in combination, a plurality of convertible type, a series of impression elements one for each type, means for operating said elements successively to print characters 55 formed successively by said type, said means including a plurality of control members arranged to be supported in two different positions to govern the direction of progression of the printing operation, a carrier for supporting said members 60 in said two positions comprising a plate, a pair of shiftable supports for said plate, a pair of rack 70 bars for operating said supports simultaneously, and means for selectively operating said rack bars to impart a shifting movement to said plate.

bars for operating said supports simultaneously, and means for selectively operating said rack bars to impart a shifting movement to said plate, said last mentioned means comprising a power driven cam means, and selectively controlled means for rendering said cam means effective as to either of said rack bars.

128. In a printer having a series of convertible type and a series of impression elements therefor, means for operating said impression elements 10 successively in a progressive order, and means for controlling the direction of progression comprising a shiftable member arranged to occupy either of two positions according to the direction of progression desired, cam means, key controlled 15 means for initiating a cycle of operation of said cam means and controlling the operation of said type-forming means, and other key controlled means for rendering said cam means effective to change the position of said shiftable member, 20 said member having two operating elements, and said other key controlled means including two push rods each operatively associated with said cam means and selectively positioned to render one or the other of said operating elements 25 effective.

129. A printer comprising, in combination, a series of impression elements, means for actuating said elements successively in progressive order comprising a printing bar having an operating member for each of the elements, said elements normally occupying a position in which their respective operating members are ineffective, means operable as an incident to the movement of one of said elements to condition an adjacent 30 element for operation by its operating member, and separate means for conditioning said one element.

130. A printer comprising, in combination, a series of impression elements, means for actuating 40 said elements successively in progressive order comprising a printing bar having an operating member for each of the elements, said elements normally occupying a position in which their respective operating members are ineffective, 45 means operable as an incident to the movement of one of said elements to condition an adjacent element for operation by its operating member, and separate means for conditioning the first of said elements in said series.

131. A printer comprising, in combination, a series of impression elements, means for actuating 50 said elements successively in progressive order comprising a printing bar having an operating member for each of the elements, said elements normally occupying a position in which their respective operating members are ineffective, 55 means operable as an incident to the movement of one of said elements to condition an adjacent element for operation by its operating member, and manually operable means for selectively conditioning any of said elements.

132. A printer comprising, in combination, a series of impression elements, means for actuating 60 said elements successively in a progressive order comprising a plurality of operating members one for each of the elements, said elements normally occupying a position in which their respective operating members are ineffective, means operable as an incident to the movement of one 70 of said elements to condition an adjacent element for operation by its operating member, and a hand lever mounted for movement into operative association with said elements to condition them selectively.

133. A printer comprising, in combination, a series of impression elements, means for actuating said elements successively in a progressive order comprising a plurality of operating members 5 one for each of the elements, said elements normally occupying a position in which their respective operating members are ineffective, means operable as an incident to the movement of one of said elements to condition an adjacent element 10 for operation by its operating member, and a key controlled power driven means for actuating the first of said elements in said series to condition it for operation by said actuator.

134. A printer having a plurality of type, a series of impression elements one for each type, a conditioning element for the first impression element in said series, a power driven means, and control mechanism for effecting the successive operation of said impression elements by 20 said power means, said control mechanism comprising a plurality of permutation elements, and means controlled by certain of said permutation elements for effecting the operation of said conditioning element by said power means.

135. In a printer having type forming means comprising a plurality of convertible type and a series of impression elements for said type, power driven means including a clutch having a control member, a keyboard having a plurality of 30 keys, means operable in response to the depression of said keys to initiate successive operating cycles by the operation of said clutch, each of said keys having a codal element, a plurality of permutation elements certain of which are operative to control said type forming means, and means controlled by others of said permutation elements to control the operation of said impression elements.

136. A printer comprising, in combination, a type forming means having a plurality of convertible type, a plurality of anvils mounted for movement toward and from said type, a power driven shaft having a cycle controlling clutch, a reciprocating printing bar operatively connected 40 with said shaft for actuating said anvils, means controlling the operation of said anvils in successive operating cycles of said bar to effect their progressive operation, a selecting mechanism including a keyboard comprising a plurality of 45 character keys and a plurality of function keys, means operable upon the depression of any of said keys to actuate said clutch to initiate an operating cycle of said shaft, each of said keys having a codal element, a plurality of permutation elements controlled by said codal elements, certain of said permutation elements being operable in response to the depression of the character keys to govern the operation of said type-forming means, and certain other of said permutation elements being controlled by said function 50 keys and adapted to govern the operation of said anvil control means.

137. In a printer having a series of convertible type and a plurality of anvils arranged for movement toward and from said type, one of said anvils having an operating member, a rock shaft, an actuating member connected with said rock shaft, power driven means, a plurality of selectively operable codal elements each adapted to 60 initiate the operation of said power driven means through an operating cycle, and a plurality of permutation elements controlled by said codal elements, certain of said permutation elements being adapted to effect an operative connection between said rock shaft and said power means

and to establish an operative connection between said operating member and said actuating member.

138. In a printer having type-forming means comprising a plurality of convertible type, impression mechanism comprising a series of reciprocable elements, power driven means including a clutch having a control member, a keyboard having a plurality of keys, means operable in response to the depression of said keys 10 to initiate successive operating cycles by the operation of said clutch, each of said keys having a codal element, a plurality of permutation elements certain of which are operative to control said type forming means, and means controlled by others of said permutation elements to control the operation of said reciprocatory elements, one of said elements having an operating member, and certain of said permutation elements being operative to effect a connection 15 between said operating member and said power driven means.

139. In a printer having a plurality of convertible type and impression mechanism comprising a series of anvils mounted for movement in a direction toward and from said type, a power driven means, an operating member for one of said anvils, an actuating member connected with said power driven means and movable into and out of association with said operating member, and key controlled means adapted to govern the operation of said power driven means and to control the connection between said operating member and said actuating member, said key controlled means including a key operated codal element and a plurality of permutation elements controlled by said codal element, one of said permutation elements being operative to control said connection between said operating member and its actuating member.

140. In a printer having a plurality of convertible type and impression means including a series of anvils mounted for movement in a direction toward and from said type, a power driven means, an operating member for one of said anvils, an actuating member connected with said power driven means and movable into and out of association with said operating member, and key controlled means adapted to govern the operation of said power driven means and to control the connection between said operating member and said actuating member.

141. A printer having, in combination, type-forming means, a power driven shaft, a clutch adapted to be tripped to initiate an operating 55 cycle of said shaft, a keyboard having a plurality of character keys and a plurality of function keys, means controlled by certain of said keys for operating said type-forming means selectively, a set of permutation elements adapted 60 to be set under the control of said character keys in different type-forming combinations, a plurality of control mechanisms adapted for operation by said shaft, and a second set of permutation elements controlled by said function keys 65 and operative to govern the operation of said control mechanisms, certain of said second set of permutation elements being adapted to be controlled by a plurality of said function keys.

142. In a machine of the character set forth, a power driven means, a plurality of control mechanisms to be operated by said power means, a plurality of codal elements arranged for operation selectively, and a series of permutation elements controlled by said codal elements, said 75

permutation elements being operative to effect the operation of their respective control mechanisms by said power means when such permutation elements are blocked by one or more of said codal elements.

143. In a machine of the character set forth, a power driven shaft, a clutch adapted to be tripped to initiate an operating cycle of said shaft, a plurality of control mechanisms, a plurality of codal elements arranged for operation selectively, a series of permutation elements controlled by said codal elements, each of said control mechanisms comprising a part to be operated and an operating member arranged for actuation by said shaft in each cycle of operation thereof, and each of said permutation elements being operative when blocked by one or more of said codal elements to establish an operative relation between one of said parts to be operated and its operating member.

144. A printer having a plurality of type, a series of impression elements one for each type, a conditioning element for the first impression element of said series, a power driven means, and a control mechanism for governing the operation of said elements by said power means, said control mechanism comprising a plurality of permutation elements, a plurality of keys each having a codal element cooperative with said permutation elements to govern the operation thereof and including a line key, and means controlled by certain of said permutation elements in response to the operation of said line key to effect the operation of said conditioning element by said power means.

145. A printer having a plurality of type, a series of impression elements one for each type, a conditioning element for the first impression element of said series, a paper feed device, and a control mechanism for governing the operation of said elements by said power means, said control mechanism comprising a plurality of control members, a plurality of keys each having a codal element cooperative with said control members to govern the operation of the latter and including a line key, and means controlled by certain of said permutation elements in response to the operation of said line key to effect the operation by said power means of said conditioning element and said paper feed device.

146. A printer having a plurality of type, a series of impression elements one for each type, mechanism for controlling the operation of said impression elements by said power means, and a paper feed device, said mechanism comprising a plurality of control members, a plurality of keys each having a codal element cooperative with said control members to govern the operation of the latter and including a paper feed key, and means controlled by certain of said permutation elements in response to the operation of said paper feed key to effect the operation by said power means of said paper feed device.

147. A printer having a plurality of type, a series of impression elements one for each type, a conditioning element for the first impression element of said series, and a control mechanism for governing the operation of said impression elements by said power means, said control mechanism comprising a plurality of control elements one for each of said impression elements adapted for individual movement, a restoring ball for said control elements, a plurality of permutation elements, a plurality of keys each having a codal element cooperative with said permutation ele-

ments and including a line key, and means controlled by certain of said permutation elements in response to the operation of said line key to effect the operation by said power means of said conditioning element and said restoring ball. 5

148. A printer having a plurality of type, a series of reciprocatory impression anvils one for each type, a conditioning anvil for the first impression anvil of said series, and a control mechanism for governing the operation of said impression elements by said power means, said control mechanism comprising a plurality of pivotal latch members one for each of said anvils adapted for individual movement, a restoring ball for the latch members of the impression anvils, a plurality of permutation elements, a plurality of keys each having a codal element cooperative with said permutation elements, and means controlled by certain of said permutation elements in response to the operation of one of said keys to effect the operation by said power means of said conditioning anvil and said restoring ball. 10 15 20

149. A printer having a plurality of type, a series of impression elements one for each type, a power driven means, and a control mechanism 25 for governing the operation of said impression elements by said power means, said control mechanism comprising a plurality of control elements one for each of said impression elements adapted for individual movement, a restoring ball for said 30 control elements, a selecting element for each of said impression elements, a plurality of permutation elements, a plurality of keys each having a codal element cooperative with said permutation elements and including a tabulating key, and 35 means controlled by certain of said permutation elements in response to the operation of said tabulating key to effect the operation by said power means of said restoring ball and one of said selecting elements. 40

150. A printer having a plurality of type, a series of impression elements one for each type, a power driven means, a control mechanism for governing the operation of said impression elements by said power means, and a selecting element 45 for each of said impression elements, said control mechanism comprising a plurality of permutation elements, a plurality of keys each having a codal element cooperative with said permutation elements and including a tabulating key, 50 and means controlled by certain of said permutation elements in response to the operation of said tabulating key to effect the operation by said power means of one of said selecting elements. 55

151. A printer having a plurality of type, a series of impression elements one for each type, a power driven means, and a control mechanism for effecting the successive operation of said elements by said power means, said control mechanism comprising a conditioning member for each 60 of said elements, a plurality of permutation elements, a plurality of keys each having a codal element cooperative with said permutation elements to govern the operation thereof, and means controlled by certain of said permutation elements to effect the operation by said power means of one of said conditioning members. 65

152. A printer having a plurality of type, a plurality of impression elements, a conditioning element for each of said impression elements, a power driven means, a plurality of permutation elements, and means controlled by said permutation elements for effecting the selective operation of said conditioning elements by said power means. 70 75

153. In a tabulating mechanism for selectively determining the position in a line at which printing is to begin, the combination of a member for each position in the line, a series of code bars operatively associated with said members, power driven means for setting said code bars in permutational combinations to operate said members selectively, and manually operable means for initiating the operation of said power driven means.

154. In a tabulating mechanism for selectively determining the position in a line at which printing is to begin, the combination of a member for each position in the line, a series of code bars operatively associated with said members, an element having a plurality of positions and operative in each position to set said code bars in a different combination to operate said members selectively, and manually operable means for initiating the movement of said element from one position to another.

155. In a page printing mechanism, the combination of printing elements and means for selectively operating the same to print a succession of characters forming a line, and means for selectively determining the position on the page at which a character is to be printed, said means comprising a series of combination bars each adapted when operated to initiate printing in a particular position, a series of code bars operatively associated with said combination bars, and means for setting said code bars in permutational combinations to operate said combination bars selectively.

156. In a page printing mechanism, the combination of printing elements and means for selectively operating the same to print a succession of characters forming a line, and means for selectively determining the position on the page at which the first character is to be printed in a line, said means comprising a series of combination bars each adapted to initiate printing in a particular position, a series of code bars operatively associated with said combination bars, a device adapted to assume any one of a plurality of positions and operative as an incident to its movement from one position to another for setting said code bars in different combinations to operate said combination bars selectively, and power operated means for moving said device from one position to another.

157. In a page printing mechanism, the combination of printing elements and means for selectively operating the same to print a succession of characters forming a line, and means for selectively determining the position on the page at which the first character is to be printed in a line, said means comprising a series of combination bars each adapted when operated to initiate printing in a particular position, a series of code bars operatively associated with said combination bars, a device adapted to assume any one of a plurality of positions and operative as an incident to its movement from one position to another for setting said code bars in different combinations to operate said combination bars selectively, power operated means for moving said device from one position to another, and manually operable means for initiating the operation of said power driven means.

158. A printer having a plurality of type, a plurality of impression elements individual to said type, and key controlled means for selecting any one of said impression elements including a group of codal elements adapted to be set in different

combinations, and a plurality of combination bars coacting with said codal elements and operatively associated with the respective impression elements.

159. A page printer having a printing head carrying a plurality of type, selectively operable means normally effecting the successive printing by said type of a line of characters, and tabulating means adapted to control said selectively operable means to effect printing at one of a plurality of character positions in the line comprising a plurality of combination bars one for each of said character positions, and a series of codal elements adapted to be set in various combinations to govern the operation of said combination bars selectively.

160. A page printer having a series of printing elements one for each character position in a line, and means for governing the operation of said elements to select any one of a plurality of tabular positions in such line, said means comprising a plurality of combination bars one for each tabular position, a series of codal elements, and key-controlled means for setting said codal elements in different combinations to govern the operation of said codal elements selectively.

161. A page printer having a series of printing elements arranged for endwise sliding movement, selectively operable means for successively actuating said elements in a predetermined order of progression, and a tabulating mechanism operative to control said selectively operable means to effect printing in tabular form, and comprising a series of permutation elements adapted to be set in different combinations, and a plurality of combination bars operatively associated with said printing elements but permitting independent movement thereof.

162. A page printer having a series of printing elements arranged for endwise sliding movement, selectively operable means for successively actuating said elements in a predetermined order of progression, and a tabulating mechanism operative to control said selectively operable means to effect printing in tabular form, and comprising a series of permutation elements adapted to be set in different combinations, a plurality of combination bars operatively associated with said printing elements but permitting independent movement thereof, and power actuated key-controlled means for governing the operation of said combination bars.

163. A page printer having a series of printing elements arranged for endwise sliding movement, selectively operable means for successively actuating said elements in a predetermined order of progression, and a tabulating mechanism operative to control said selectively operable means to effect printing in tabular form, and comprising a series of permutation elements adapted to be set in different combinations, a plurality of combination bars operatively associated with said printing elements but permitting independent movement thereof, and power actuated key-controlled means for selectively operating said permutation elements to set them in different combinations successively.

164. In a printing mechanism adapted for printing matter on a sheet in tabular columns, the combination of printing elements, means for selectively operating said elements to print successive characters, and means for controlling the position on the sheet at which printing is to be effected comprising a device having a control position for each tabular column and operative in

each of said positions to effect printing in the corresponding tabular column, and a key adapted to be actuated repeatedly for advancing said device to said positions successively.

5 165. A printer having convertible type comprising a plurality of delineating elements disposed in a common plane and movable in said plane to form different characters, means for supporting a writing medium in printing relation to said 10 elements, impression means, and power driven mechanism for positioning said delineating elements to form characters and for effecting relative motion between said elements and said impression means, said power driven mechanism including cam means operative to compress said writing medium between the elements and said impression means with a predetermined pressure.

166. A printer comprising a printing head having a plurality of type spaced apart lengthwise 20 of the head, a printing bar mounted for movement toward and from said head, a series of impression elements one for each type, means on said bar adapted for connection selectively with said impression elements to move them toward said head, and power driven cam means for actuating said bar and operative to compress writing and inking media between said type and said impression elements with a predetermined pressure.

20 167. In a printer having a series of printing elements, a power driven actuator, means normally operable as an incident to the operation of one of said elements to condition an adjacent element for movement by said actuator, and key 25 controlled power driven means operative to render said actuator ineffective as to said conditioned element.

168. In a printer having a series of printing elements, a power driven actuator, means normally operable as an incident to the operation of one of said elements to condition an adjacent element for movement by said actuator, key-controlled power drive means operative to condition one of said elements independently of the 45 operation of an adjacent element, and means controlled by the last mentioned means operative to render said actuator ineffective as to the normally conditioned element.

169. In a printer having a series of printing 50 elements, a power driven actuator, means normally operable as an incident to the operation of one of said elements to condition an adjacent element for movement by said actuator, key-controlled power driven means operative to condition one of said elements independently of the 55 operation of an adjacent element, and means controlled by the last mentioned means operative to render said actuator ineffective as to the normally conditioned elements, each of said elements having a latch member for retaining it in such 60 conditioned relation to the actuator, and said last mentioned means including a power driven member for operating said latch members when in active position relative to their respective elements.

170. A printer comprising a printing head having a plurality of convertible type, selectively operable means for converting all of said type simultaneously to form one of a plurality of characters, and means operative to effect a printing operation by a plurality of said type simultaneously.

70 171. A printer comprising two recording units each adapted to support a record sheet, a printing head common to said two units and having

a plurality of convertible type, means for converting all of said type simultaneously to form one of a plurality of characters, and impression means operable to print such simultaneously formed character on both of said record sheets. 5

172. A printer comprising two recording units each adapted to support a record sheet, a printing head common to said two units and having a plurality of convertible type, means for converting all of said type simultaneously to form 10 one of a plurality of characters, an impression mechanism for each unit, each comprising a series of printing elements and selectively controlled power driven actuating means therefor.

173. A printer comprising two recording units 15 each adapted to support a record sheet, a printing head common to said two units and having a row of convertible type for each unit, an impression mechanism for each unit operable in successive cycles to print successively formed type 20 in a predetermined order of progression, and one of said units having selectively operable means for converting all of said type simultaneously.

174. In page printing apparatus, in combination, printing mechanism, means for operating said mechanism selectively to print a succession of characters forming a line, and tabulating means for determining the position in the line at which a character is to be printed comprising a 30 series of codal elements adapted to be set in a different combination for each position in the line, means for setting said elements, and means controlled by said elements for conditioning said mechanism to print at the position corresponding to the setting of the elements. 35

175. In a page printing apparatus, in combination, printing mechanism, means for operating said mechanism selectively to print a succession of characters forming a line, and tabulating means for determining the position in the line at which a character is to be printed, said tabulating means comprising a series of combination bars selectively operable to effect printing in any selected position in the line, a series of code bars 45 operatively associated with said combination bars, and means for setting said code bars in different combinations to operate said combination bars selectively.

176. In a tabulating mechanism for selectively determining the position in a line at which printing is to be effected, in combination, a series of code elements adapted to be set in a different combination for each position in the line, means for setting said code elements, and means controlled by said elements for initiating printing in the position corresponding to the setting of the elements. 50

177. In a tabulating mechanism for selectively determining the position in a line at which printing is to be effected, in combination, a series of code elements adapted to be set in a different combination for each position in the line, a setting device having a plurality of positions and operative in each position to set said elements in a particular combination, manually controlled means for moving said device from one position to another to effect a desired setting of said elements, and means controlled by said elements for initiating printing in the position corresponding 60 to the setting of the elements. 65

178. In a tabulating mechanism for selectively determining the position in a line at which printing is to be effected, in combination, a series of code elements adapted to be set in a different 70 75

combination for each position in the line, a setting device having a plurality of positions and operative in each position to set said elements in a particular combination, a manually operable key, means actuated in response to the operation of said key for moving said device step-by-step from one position to the next to vary the setting of said elements, and means controlled by said elements for effecting printing in the position corresponding to the setting of the elements.

179. In a selectively operable mechanism, the combination of a series of combination bars, a series of code bars operatively associated with said combination bars and adapted to be set in different combinations to operate the combination bars selectively, a multi-position setting device for said code bars, said device having means operative in each position to set the code bars in a predetermined combination, and manually controlled means for moving said device from one position to another.

180. In a printing mechanism having convertible type comprising a plurality of delineating elements disposed in a common plane and movable in said plane to form different characters, the combination of an impression element for said type, an inking medium disposed between said element and said type, and means for effecting relative movement between said type and said element to compress said inking medium and a writing medium between the type and the impression element with a predetermined pressure.

181. A printer having, in combination, character printing mechanism, a power driven shaft, a clutch adapted to be tripped to initiate an operating cycle of said shaft, a keyboard having a plurality of character keys and a plurality of function keys, means for selectively controlling said printing mechanism comprising a series of permutation elements adapted to be set under the control of said character keys in different character selecting combinations, a plurality of control mechanisms adapted for operation by said shaft, and a second set of permutation ele-

ments controlled by said function keys and operative to govern the operation of said control mechanisms, certain of said second set of permutation elements being adapted for control by a plurality of said function keys.

182. In a tabulating mechanism, in combination, a plurality of combination bars, a series of code bars, a device operative to set said code bars in different combinations to effect the selection of certain of said combination bars, and key controlled means for rendering said device effective.

183. A selectively operable mechanism comprising, in combination, a series of elements adapted to be set selectively in different permutational combinations each representative of a different character position in a line of composed matter, and means for selectively setting said elements in any one of said combinations.

184. A selectively operable mechanism comprising, in combination, a series of elements adapted to be set selectively in different permutational combinations each representative of a character position in a line of composed matter, and power-driven key-controlled means for selectively setting said elements in any one of said combinations.

185. In a selectively operable mechanism, in combination, a series of elements to be actuated individually, a power-driven actuator for said elements, selectively operable means for conditioning any one of said elements for actuation, and means operable as an incident to the actuation of said one element for conditioning the adjacent element for actuation.

186. In a selectively operable mechanism, in combination, a series of elements to be actuated individually, a power-driven actuator for said elements, selectively operable means for conditioning any one of said elements for actuation, and selectively controlled means operated as an incident to the actuation of said one element for conditioning either adjacent element for actuation.

HOWARD D. COLMAN.
